GRINDING MACHINE

Maxwell I. Mathewson and August L. Krause,
Providence, R. I., assignors to Brown and
Sharpe Manufacturing Company, a corpora-
tion of Rhode Island

Application November 14, 1935, Serial No. 49,772

89 Claims. (Cl. 51—95)

The present invention relates to improvements in grinding machines.

It is a principal object of the invention to provide a grinding machine of novel and improved construction which is well adapted for the performance of accurate and dependable work over a wide range of operating conditions, and for either manual or automatic control.

It is another object of the invention to provide in a grinding machine of the general type herein described, a novel and improved control system which effects a more effective coordination in the operation of the several operating units of the machine, than has heretofore been achieved, and which is particularly constructed and arranged to permit of a centralized and automatic control of the several units of the machine in accordance with any one of a number of different operating cycles as required for different classes of work.

It is a further object of the invention to modify and improve certain of the operating mechanisms in a machine of the general type herein disclosed to secure a more efficient and satisfactory operation of the several cooperating units, and particularly to adapt the several mechanisms for automatic control in connection with applicant's control system hereinafter set forth.

The invention is herein disclosed in a preferred form in a grinding machine of the general type which comprises a longitudinally movable work table having supported thereon a rotatable work holder in the form of the usual head stock and tail stock, a power driven grinding wheel spindle, a wheel spindle carriage which is supported on cross ways for movement toward and away from the work, and cross feed connections for moving the carriage at either a feeding or rapid rate toward and away from the work.

The head stock and work table of the present machine are driven from separate direct current motors which are controlled by field rheostats to permit a wide latitude in the rate of drive. The head stock motor is carried on the head stock casing, and is connected through reduction gears and a silent chain drive to provide a novel and efficient self-contained driving unit. The table motor is reversible to reverse the direction of drive, and is connected through a power hand clutch and a fast-slow clutch in series therewith, so that alternate fast and slow driving rates are available for either power or manual operation of the table.

Reciprocation of the table is controlled by means of reversing dogs on the table which co-

operate with a reversing lever to reverse the table motor. In the illustrated machine, a novel arrangement of reversing switches and operating connections therefor from the reversing lever is provided which is particularly well adapted to limit the overrun of the table upon reversal within ascertainable limits. The connections provided comprise a right and a left limit or reversing switch, and right and left slow-down switches which are controlled by means of a cam actuated by the movement of the reversing lever from one operating position to the other. With the arrangement described, each of the slow-down and reversing switches is rendered operative when the reversing lever reaches a predetermined angular position, so that the table is electrically slowed and then stopped in a position which corresponds to the angular position reached by the reversing lever, and may be determined within narrow limits through the operation of the electrical braking connections hereinafter described.

In order to provide a positive limit for movement of the table in each direction where it may be desired to move the grinding wheel beyond the normal stop position against or closely adjacent a shoulder on the work, two positive stops are provided on the machine frame, which are arranged to engage with and positively stop movement of the table and reversing lever in each direction when moved manually an appreciable distance beyond the normal stop position. With the present construction, the table slow-down switches are connected to slow down the table only when the fast-slow clutch is in its high speed position.

Features of the machine herein described and illustrated, but not claimed, relating particularly to the operating and control devices for imparting translatory movements to the reciprocating work table form the subject-matter of a divisional application Serial No. 167,190, filed October 4, 1937.

The cross feed mechanism provided with the present construction for feeding the wheel spindle carriage toward and away from the work, comprises a rotatable feed screw and a hand wheel adjustably connected thereto for manual operation of the feed. Automatic operation is secured by means of a reciprocating pawl which is arranged for engagement with ratchet teeth formed on the hand wheel. In accordance with one feature of the present invention, a dwell surface or bare spot is provided in the ratchet teeth to limit the feed to depth. Inasmuch as the ad-

vancing movement of the hand wheel under the influence of the pawl is thus always stopped at exactly the same point, it will readily be seen that with the construction illustrated an extremely fine adjustment of the depth power feed to any desired fraction of a tooth of the ratchet, may be obtained by disconnecting and turning the hand wheel back the desired amount.

With the present construction, the pawl may be connected for continuous reciprocation through driving connections from the table motor, or may have imparted thereto an intermittent feed motion which is controlled by the table reciprocation through connections actuated by the table reversing lever.

In connection with the cross feed mechanism above described, there is provided a novel control device in the form of two stop pins on the cross feed hand wheel, a control slide provided with actuating cam and stop surfaces arranged in the path of said pins, and a control switch which may be operatively connected to control certain other operating units of the machine. This control device may be rendered operative during the manual operation of the cross feed to positively limit the feeding and backing-off movements imparted to the wheel spindle carriage, and also to prevent the rapid advance of the grinding wheel into interfering engagement with the work, and is also arranged to operate in connection with the electrical control system hereinafter described, to provide for an automatic control of the starting and stopping of the several cooperating units of the machine from the cross feed hand wheel.

In accordance with another feature of the present invention, a novel and improved mechanism is provided for imparting to the grinding wheel spindle carriage, a rapid movement through a predetermined distance toward and away from the work. This mechanism comprises specifically a reciprocable lever and yielding spring connections for moving the feed screw axially in either direction through an exactly predetermined distance. The reciprocable lever is actuated from a crank shaft to which is imparted successive 180° increments of rotation alternatively to advance and to retract the carriage by means of an electric motor driving and braking unit.

Further in accordance with the present invention, an adjustable cam is provided on the crank shaft for stopping the motor and applying the brake, so that the crank shaft may be stopped in each of its alternative positions corresponding to the extreme throw of the actuating lever in each direction. With this construction and mode of operation of the quick traverse movement including the yielding spring connection between the lever and the axially movable feed screw, an exact positioning of the carriage in either its forward or back position, is secured regardless of minor variations in the angular stop position of the crank shaft.

With the present construction, separate driving motors are provided for supplying lubricant to the various bearings of the machine, and for supplying coolant to the point of grinding contact with the work. The supply of coolant is controlled by means of a valve which is actuated by a solenoid alternatively to turn on or shut off the supply of coolant. The grinding wheel spindle is continuously driven at a high rate of speed during the operation of the machine, by

means of a separate motor through a belt drive which may be of any ordinary description.

In carrying out the present invention, a novel and improved system of controls has been provided which is arranged in conjunction with the several mechanical and electrical features herein set forth to secure a more completely automatic operation of the machine, to permit the rapid setting up of the machine and subsequent control by the operator of the several operating units for the performance in an accurate and dependable manner of any desired cycle of operations.

The control devices include a main starting and stopping control switch for the machine which serves to control the operation of the main grinding wheel motor, the oil pump motor, the coolant pump motor, and a generator motor which drives a head stock generator and a table generator, which in turn supply power for the head stock and table motors and the direct current control circuit hereinafter to be described. Separate control knobs are provided for controlling the operation of the head stock and table, and also the cross feed rapid movement of the wheel spindle carriage.

With the present machine there are also provided a number of manually operable switch controls which enable the operator readily to set up the machine for a number of different operating cycles. In order to enable the operator simultaneously to start the head stock and table reciprocation, an automatic control switch is provided which may be set to bring the table motor under the control of the headstock control knob.

In order to provide for a substantially automatic operation of the machine, as for instance, where similar grinding operations are to be performed successively upon identical work pieces, a manually operable switch control is provided which may be set to bring the head stock, coolant, table, and cross feed rapid movement under the control of the cross feed hand wheel, so that the manipulation of the hand wheel in advancing the grinding wheel toward the work, serves to start the operation of the several cooperating units, and the movement of the hand wheel in backing off the grinding wheel similarly serves to arrest the operation of these units to permit the placing of a new work piece in the machine.

In order to set up the machine for plunge grinding, there is provided a table run-stop switch which acts when moved to stop position to disable the connections for shifting the power-manual clutch to power position, so that there can be no possibility of injury to the machine or work through the accidental starting of the table.

In order to set up the machine for the operation of truing the grinding wheel, there is provided a true grinding control knob which operates when moved to truing position to shift the control of the several cooperating units of the machine, so that these units can operate only in the desired manner to perform the truing operation irrespective of any possible accidental or unskilled manipulation of the several machine controls while the truing operation is being performed.

For the convenience of the operator in manipulating the machine, there are also provided separate manual control switches for determining the position of the fast-slow table clutch respectively for power and for manual operation of the table. The control circuits of which these switches are a part, are so arranged that the con-

trol of the slow-fast clutch is automatically shifted from one to the other of these switches as the power-manual clutch is shifted from power to manual position, and vice versa. In order to control the amount of the table dwell, there is provided a control switch which may be located in any one of three operating positions to provide a long, or medium, or extremely short dwell at the end of the table movement in each direction according to the character of the work and the rate at which the table is being driven.

The several features of the present invention consist also in the devices, combinations and arrangement of parts hereinafter described and claimed, which together with the advantages to be obtained thereby, will be readily understood by one skilled in the art from the following description taken in connection with the accompanying drawings, in which Fig. 1 is a view in front elevation of a grinding machine embodying the several features of the invention; Fig. 2 is a view in left side elevation of the machine; Fig. 3 is an enlarged detail view of the solenoid controlled coolant valve shown in Fig. 2, the parts being shown in section to illustrate the construction thereof; Fig. 4 is a plan view from beneath, of substantially the parts shown in Fig. 3; Fig. 5 is a view of the head stock unit looking from the right, the supporting table structure being shown in section, and a portion of the head stock drive being shown in section; Fig. 6 is a sectional view taken on the line 6—6 of Fig. 5; Fig. 7 is an enlarged view in front elevation illustrating particularly the table drive, overlying portions of the machine having been broken away to show underlying parts; Fig. 8 is a sectional view taken substantially on the line 8—8 of Fig. 7, being a somewhat modified plan view of the table driving connections; Fig. 9 is a sectional view taken on the line 9—9 of Fig. 7, to illustrate particularly the power-manual clutch and solenoid control therefor; Fig. 10 is a sectional view taken on the line 10—10 of Fig. 7, illustrating particularly the table slow-fast clutch and solenoid control therefor; Fig. 11 is an enlarged detail view in front elevation with certain overlying parts broken away to illustrate particularly the reversing lever and reversing switch mechanism therefor, the parts being illustrated in a hypothetical half-way position; Fig. 12 is a sectional view taken on the line 12—12 of Fig. 11; Fig. 13 is a detail sectional view taken on the line 13—13 of Fig. 12, showing the mechanism for reciprocating the cross feed pawl actuating crank from the reversing lever; Fig. 14 is an enlarged detail view in front elevation, of the cross feed hand wheel unit including the power cross feed pawl and actuating crank, and control slide; Fig. 15 is a sectional view in left elevation taken on the line 15—15 of Fig. 14; Fig. 16 is a detail sectional view taken on the line 16—16 of Fig. 15, to illustrate particularly the control slide; Fig. 17 is a sectional view in rear elevation taken on the line 17—17 of Fig. 15, showing particularly the relationship of the cross feed hand wheel and slide; Fig. 18 is a plan view of the parts shown in Fig. 14; Fig. 19 is a sectional plan view taken on the line 19—19 of Fig. 16; Fig. 20 is an enlarged detail view in rear elevation and with certain portions of the machine broken away to illustrate particularly the mechanism for imparting cross feed rapid movement to the wheel spindle carriage; Fig. 21 is a detail sectional view taken on the line 21—21 of Fig. 20, to illustrate particularly the crank shaft for imparting rapid movement to the wheel

spindle carriage, and the starting and stopping switch control mechanism therefor, the parts being shown in the positions taken when the carriage is moved to its fully advanced position; Fig. 22 is a view similar to Fig. 21, with the parts shown in the positions taken with the carriage in its fully retracted position; Figs. 23 is a sectional view taken on the line 23—23 of Fig. 20, and illustrating particularly the cross feed screw and connections for imparting cross feeding and rapid movement to the wheel spindle carriage; Fig. 24 is a detail sectional view forming a downward continuation of Fig. 23, to illustrate particularly the motor and braking mechanism for the wheel spindle carriage rapid movement; Fig. 25 is a sectional view taken on the line 25—25 of Fig. 24, illustrating particularly the solenoid for controlling the brake; Fig. 26 is a sectional view in front elevation taken on the line 26—26 of Fig. 23, to illustrate particularly the grinding wheel spindle and driving connections therefor; Fig. 27 is a sectional view illustrating in detail a portion of the mechanism shown in Fig. 26, to illustrate particularly the mechanism for reciprocating the grinding wheel spindle; Fig. 28 is a sectional view taken on the line 28—28 of Fig. 27; Fig. 29 is a plan view of the parts shown in Fig. 27; Fig. 30 is a sectional view taken on the line 30—30 of Fig. 27; Fig. 31 is a sectional view taken on the line 31—31 of Fig. 27, to illustrate particularly the solenoid control for starting and stopping spindle reciprocation; Fig. 32 is a developed view on an enlarged scale, of a portion of the spindle reciprocation clutch control cam shown in dotted lines in Fig. 28; Fig. 33 is an enlarged view in front elevation illustrating particularly the left half of the control panel for the machine, a portion thereof being broken away to illustrate particularly the switches controlled by the head stock and table knobs; Fig. 34 is a sectional view taken on the line 34—34 of Fig. 33, to illustrate certain of the control elements on the panel including the main starting and stopping switch, the head stock motor rheostat, the hand wheel fast-slow switch, and the automatic cross feed hand wheel control switch; Fig. 35 is a sectional view taken on the line 35—35 of Fig. 33, illustrating particularly the connections for controlling the head stock starting, stopping and jog switches from the head stock knob; Fig. 36 is a sectional view taken on the line 36—36 of Fig. 35, illustrating on an enlarged scale the head stock jog switch; Fig. 37 is a detail sectional view looking from below, taken on the line 37—37 of Fig. 33, to illustrate on an enlarged scale the head stock stopping switch; Fig. 38 is a sectional view looking from below, taken on the line 38—38 of Fig. 33, to illustrate particularly the table starting switch; Fig. 39 is a sectional view taken on the line 39 of Fig. 33, to illustrate particularly the head stock starting switch; Fig. 40 is an enlarged view in front elevation of the right hand half of the control panel for the machine, a portion of the panel being broken away to show particularly the table reversing switches, and the control switches actuated by the spindle carriage rapid movement control knob; Fig. 41 is a sectional view taken on the line 41—41 of Fig. 40, to illustrate certain of the control mechanisms for the machine including the connections for operating the rapid movement forward and back switches from the rapid movement control knob, the table motor rheostat, the plunge cut control switch, and the table dwell switch; Fig. 42 is a sectional view taken on the line 42—42 of Fig. 40, to illustrate

particularly the connections for actuating the truing control switch from the truing control knob; Figs. 43 to 46 inclusive, are similar views of the table reversing switch connections illustrated in Fig. 40, and with Fig. 40 illustrate in five successive steps the positions taken by said switch connections during the movement of the reversing lever to reverse the direction of table drive from right to left; Figs. 47 and 48 constitute a wiring diagram of the electrical connections for the machine, Fig. 47 illustrating particularly the electrical connections on the machine control panel, and Fig. 48 illustrating the subsidiary switch connections controlled thereby for controlling the operation of the several operating units of the machine; and Figs. 49 and 50 constitute an explanatory diagram of the electrical connections, Fig. 49 being an explanatory diagram of the electrical connections for certain of the operating units, and Fig. 50 being an explanatory diagram more particularly of the direct current control circuit of the machine.

The machine illustrated in the drawings as embodying in a preferred form the several features of the present invention, comprises a base 102, a work supporting table 104 which is arranged to slide in ways 106 on the base, a head stock bracket 108 adjustably secured on the table, a foot stock 110 also carried on the table, and a grinding wheel carriage 112 which is supported on cross ways 114 on the base.

The head stock unit comprises a rotary headstock of ordinary description, generally indicated at 116 (see Figs. 1, 5 and 6), and is driven from a variable speed direct current motor 118 which is carried directly on the head stock bracket 108 to provide a compact and economical driving unit. The head stock motor 118 is located on the bracket 108 with its axis at right angles to the axis of the head stock, and is connected to the headstock 116 through driving connections including a worm 120 on the armature shaft 122 of the motor, which meshes with a worm gear 123 on an intermediate shaft 124 supported on the head stock bracket 108 parallel to the axis of the headstock. The headstock is driven from the intermediate shaft 124 by means of a chain belt 126 which passes over a sprocket 128 on the shaft and a similar sprocket 130 mounted integrally to turn with the headstock. With this construction, a uniform and accurate control of the rotational speed of the headstock is obtained by the use of a relatively high speed electric motor combined with the reduction gear unit above described. Any variations in the rotational speed of the headstock which might result from imperfections or play in the cooperating worm and worm gear, are eliminated by the comparatively flexible belt drive from the drive shaft 124 to the head stock.

The work supporting table is driven from a variable speed reversible direct current motor 132 as best shown in Figs. 2, 7 and 8 of the drawings, through driving connections which comprise a pinion 134 mounted on the armature shaft 136 of the motor to mesh with a gear 138 secured to a rotatable shaft 140. The gear 138 meshes also with a sleeve driving gear 142 which is externally supported in a bearing 146, and has formed at the inner or forward end thereof a clutch face 148 for engagement with a cooperating clutch surface 150 carried on the shiftable element of the power-manual clutch. The shiftable clutch element referred to, takes the form of a shaft 152 supported for axial and rotational

movements at one end within the sleeve hub of the gear 142 and at its other end in a bearing 153 on the machine frame. Rigidly secured to the shaft 152 is a high speed driving gear 154 which has formed thereon the clutch face 150, and a slow speed driving gear 156.

In order to provide for the manual operation of the table, there is formed on the end of the shaft 152 a clutch face 160 which is arranged to engage with a clutch member 162 formed on the adjacent end of a hand wheel shaft 164 in axial alignment therewith. The shaft 164 is supported in bearings 166 in the machine frame, and carries at its outer end a table traversing hand wheel 168. At its inner end the shaft 164 is provided with an axially extending pin 170 which extends into an axial bore in the abutting end of the shaft 152 to maintain the two shafts in axial alignment.

The gears 154 and 156 mesh respectively with gears 174 and 176 which are loosely mounted to turn on a rotatable shaft 178, and form respectively the fast and slow driving elements of a fast-slow clutch unit. A driven clutch element 180 is splined to the shaft 178 between the driving gears 174 and 176, and is arranged for axial movement in either direction to engage alternatively with cooperating clutch members formed on the adjacent faces of the driving gears. A pinion 182 also secured to the shaft 178 meshes with a gear 184 secured to a drive shaft 186 which also carries the table driving pinion 188, which in turn meshes with a rack 190 formed on the under side of the table. With this construction and arrangement of parts, it will readily be seen that the table may be connected alternatively for power or manual operation by an axial shifting of the power-manual clutch shaft 152 including the gears 154 and 156. The table may then be driven selectively at a high or low rate of speed either by power or manually in accordance with the position of the fast-slow clutch 180 as desired.

The position of the power-manual clutch for the table is controlled from an electrical control system for the machine hereinafter to be described, by means of a solenoid 200 and a clutch actuating lever 202 (see Figs. 7 and 9) which is mounted to turn on a pivot shaft 204, and is connected at one end to the solenoid armature 206, and at its other end to the axially movable clutch shaft 152. The lever 202 is connected at its upper end to the clutch by means of two bearing blocks 207 which are pivotally supported on the forked upper end of the lever to engage in a peripheral groove formed in the sleeve hub 208 of the gear 154 rigidly secured to the clutch shaft 152. At its lower end the clutch lever 202 is connected to the solenoid armature 206 by means of a link 210 which is pivotally connected at one end to the armature, and is provided with a reduced portion which extends through a bore formed in a cross pin 212 supported in the forked lower end of the clutch lever. A compression spring 214 coiled about the reduced portion of the link 210 between a collar 216 and the cross pin 212, tends to maintain the clutch lever 202 yieldingly against an abutting shoulder on the link 210. The movement of the clutch lever 202 in either direction is limited by engagement with adjustable stop pins 218 and 220 screw-threaded into the machine casing, and arranged for contact with opposite sides of the lever. Two tension springs 222 connected at one end to the clutch lever 202, and at their other ends to a pin 224

on the frame, tend normally to swing the clutch lever in a clockwise direction as shown in Fig. 9, to shift the clutch in a direction to disengage the power clutch member 148 and to engage the hand wheel clutch 162. With this construction and arrangement of the parts, the energizing of the solenoid 200 will cause the clutch lever to be shifted in a counterclockwise direction against the pressure of the spring 222 to disengage the hand wheel clutch element 162 and to engage the power clutch member 148 for power operation of the table. The yielding connection provided by the spring 214 between the solenoid armature 206 and the clutch lever 202, permits the armature 206 to be moved immediately to power position upon energizing the solenoid, and thus to avoid possible injury thereto, although the actual shifting of the clutch may be delayed while the clutch teeth are brought into alignment.

The position of the slow-fast clutch member 180 is controlled from the electrical control system for the machine, by means of a solenoid 226 and a clutch actuating lever 228 (see Figs. 7 and 10) which is pivotally hung from a pivot pin 230. The clutch lever 228 takes the form of a frame on which are supported bearing blocks 232 arranged for engagement in a peripheral groove 234 formed in the clutch member 180. At its lower end the clutch lever 228 is connected to the armature 236 of the solenoid 226 by means of a link 238 having a reduced portion which extends through a bore formed in a cross pin 240 supported in the forked lower end of the clutch lever. A yielding connection is provided between the clutch lever 228 and armature 236 by means of a compression spring 241 which is coiled about the reduced portion of the link 238 between a collar 242 on the end thereof, and the cross pin 240, so that the lever 228 and cross pin 240 are held yieldingly against an abutting shoulder formed on the link 238. The fast-slow clutch 180 is normally held in its fast position by means of two parallel tension springs 244 which are connected at one end to a cross pin 246 on the lever 228, and at their other ends to a pin 248 on the machine frame. The movement of the clutch lever 228 in either direction is limited by means of adjustable stop pins 250 and 252 screwed threaded into the machine frame.

The reciprocation of the work table is controlled by means of table dogs and a reversing lever which operate through switch connections hereinafter to be described, to stop and thereafter to reverse the direction of rotation of the table motor 132. Two reversing dogs 260 and 262 are provided as best shown in Figs. 1, 11 and 12, adjustably mounted in a T-shaped slot 264, and arranged for engagement with a reversing lever 266 supported on a rock shaft 268 carried in bearings 270 on the machine frame. There are also provided on the machine frame at each side of the reversing lever, two stop lugs 272 and 274 to positively limit the swinging movement of the lever in either direction under the influence of the reversing dogs, so that a positive stop is provided for the travel of the table in either direction. The reversing lever 266 is bifurcated to fit over a flattened portion 276 formed on the rock shaft 268, and is pivotally connected thereto by means of a cross pin 278, so that the lever may be swung forwardly out of the path of the reversing dogs, to permit manual operation of the lever independently of the dogs. Secured to the rock shaft 268 is a downwardly extending hook-

shaped lever arm 280 which has formed thereon a gear segment 282 arranged for engagement with a pinion 284 secured to a control shaft 286 which is supported in bearings on the machine frame in parallel relation to the rock shaft 268. With the connections above described, the movement of the reversing lever 266 from one operating position to the other, will cause a corresponding rotational movement to be imparted to the control shaft 286 in an opposite direction by an amount which will depend exactly upon the amplitude of movement of the control lever 266. The oscillatory movements of the control shaft 286 are utilized to operate a table slowdown and reversing switch to reverse the direction of drive of the table motor, and also to impart an intermittent advancing movement to the cross feed pawl hereinafter to be described.

The switch connections which are controlled by the movement of the reversing lever 266 from one operating position to the other (see Figs. 11, 40, 43 and 45 inclusive, and 48) comprise a right slow-down switch contact 55-56 and a left slow-down switch contact 56-57 which operate to slow the motor and table driven thereby to a predetermined slow rate, and a right limit switch contact 3-63, and a left limit switch contact 3-65, which operate thereafter to reverse the motor and direction of table movement. The switch actuating connections comprise a cam 290 on a cam shaft 287 which is mounted in axial alignment with the control shaft 286 and is keyed to turn therewith. The shaft 287 is supported adjacent one end thereof in a stationary bearing in the machine frame, and at its other end is provided with an axially extending pin 288 which extends into an axial bore in the end of the control shaft 286. A pin 289 carried on an enlarged head on the shaft 287, engages with a corresponding aperture formed in the face of the gear 284, so that the cam shaft 287 is keyed to rotate therewith. Two identical switch actuating levers 292 and 294, pivoted respectively at 296 and 298 on the machine frame, are provided at their free ends with cam rolls arranged for engagement with the cam, and lugs 300 and 302 which are yieldingly engaged by two downwardly pressed switch plungers 304 and 306 for actuating the switch connections for reversing the direction of drive of the table motor. Two tension springs 308 and 310 connected respectively to the switch levers 292 and 294 tend normally to move the levers downwardly into engagement with the switch cam 290. Stop pins 312 and 314 serve to limit the downward movement of the levers. The switch plunger 304 carries two switch contacts 316 and 318 which are constructed and arranged so that when the plunger 304 occupies an intermediate position as the switch lever 292 rides on the intermediate level of the switch cam 290, both are closed. The movement of plunger 304 to its high position under the influence of the cam 290 causes the contactor 318 to move away from and open the switch contact 3-65, the movement of the plunger 304 to its low position conversely causing the contactor 316 to move away from and open the switch contact 55-56. The switch plunger 306 is similarly provided with two contactors 320 and 322 which are similarly controlled to close both contactors for an intermediate position of the switch plunger 306, and to open alternatively the left slow-down contact 56-57 or right limit switch contact 3-63 as the plunger is moved to its low or high position.

The operation of the reversing lever 266 and

reversing switch connections controlled thereby, will be readily understood from an inspection of Figs. 40, and 43 to 46 inclusive, which illustrate five successive positions of the switch connections taken as the reversing lever is shifted to reverse the direction of table travel from right to left. As shown in Fig. 40, the reversing lever is in its extreme position to the left prior to the engagement of the dog 260 therewith. For this position of the reversing lever 266, the cam 290 has been rotated in a clockwise direction so that the plunger 304 is fully raised under the influence of the high portion of the cam, and the plunger 306 is fully depressed under the influence of the low portion of the cam 290. For this position of the parts, the right slow-down switch contact 55—56 and the right limit switch contact 3—63 are closed. The movement of the reversing lever 266 upon engagement of the table dog 260 therewith, now causes the cam 290 to rotate in a counterclockwise direction. As shown in Fig. 43, the switch lever 292 is moved onto the intermediate level of the cam 290, causing the left limit switch 3—65 to be closed, but without otherwise altering the operating conditions electrically. As shown in Fig. 44, the switch plunger 304 is now moved to its retracted position as the switch lever rides from the intermediate to the low portion of the cam 290, causing the contact 316 to be disengaged from the right slow-down contact 55—56 to shift the motor to slow speed. The continued rotation of the cam 290 as the reversing lever 266 swings still further towards its limiting position to the right, now causes the switch lever 294 to ride onto the intermediate portion of the cam 290 as shown in Fig. 45, to close the left limit switch contacts 56—57, and subsequently, as the switch lever 294 rides onto the high portion of the cam 290, to disengage the switch contactor 322 from the right limit switch contact 3—63, causing the motor to be reversed. In order to shift the table travel from the left to right, the operation is exactly the reverse. The opening of the left slow-down switch contact 56—57 will cause the motor to be slowed to a predetermined speed, and the subsequent opening of the left limit switch contact 3—65 will again reverse the direction of rotation of the table motor. In order to permit the braking torque of the motor to bring the table smoothly to a stop upon reversal, and also to permit a certain amount of variation in the overrun of the table in either direction, the cam 290 and connections to the reversing lever 266 are so arranged as to permit a certain amount of overthrow of these parts after the motor has been reversed. The reversing lever 266 does not normally engage the stop abutments 272 and 274 during reversal. However, it is frequently desirable to stop the power operation of the machine at the end of its travel in either direction, and thereafter by manual operation thereof to bring the grinding wheel up to or briefly into contact with an abutting shoulder of the work. The engagement of the reversing lever 266 with one or the other of these stop abutments, will then operate to limit the continued manual movement of the table to bring the grinding wheel against the shoulder. The operation of the subsidiary electrical connections controlled by the opening of the switch slow-down and reversing contacts above described, to effect the corresponding changes in the operating conditions of the machine, will be further described in connection

with the electrical diagrams (Figs. 47 to 50 inclusive).

The cross feed mechanism of the present machine for advancing and retracting the wheel spindle carriage (see Figs. 15 and 23), comprises a cross feed nut 330 rigidly secured to the under side of the cross feed carriage, and a cooperating feed screw 332 which is supported on the machine frame for rotational feeding movement and for axial movement to impart a rapid movement to the wheel spindle carriage toward and away from the work as hereinafter more fully to be described. Rotational movements are imparted to the feed screw 332 to advance and retract the carriage by means of a gear 334 which is splined onto the feed screw 332 to rotate therewith, and is held against axial movement between the two halves of a bearing support 338 within which the feed screw is mounted for rotational and axial movement. Meshing with the gear 334 is a pinion 340 formed on the end of a shaft 342 which at its forward end carries the cross feed hand wheel 344. A collar 346 secured to the feed screw 332 provides a positive stop to limit the advancing movement of the nut 330 and carriage 112 with relation to the feed screw. A flange 348 formed on the feed screw similarly provides a positive stop to limit the retracting movement of the nut 330 and carriage with relation to the feed screw.

In accordance with certain features of the present invention, a novel and improved cross feed hand wheel unit is provided which is particularly well adapted to facilitate the manipulation of the machine by the operator. As best shown in Figs. 14 to 19 inclusive, the hand wheel unit comprises a disk gear 350 keyed to the reduced forward end of the hand wheel shaft 342, and the hand wheel 344 which is constructed of two circular plates mounted one on each side of the gear 350 to turn on the sleeve hub thereof and screwed together adjacent their peripheral edges to form a casing which entirely encloses the gear 350. The hand wheel 344 is normally connected to turn with the gear 350 and hand wheel shaft 342, and may be moved relatively thereto to secure a fine adjustment of the depth feed by means of a graduated disk 352 which is provided with a sleeve hub 354 externally supported in a bearing 356 formed on the front plate of the hand wheel 344. A pin 358 is supported within the sleeve hub 354, and at its rear end extends into a bore 360 formed in the rear plate of the hand wheel 344. Gear teeth 362 are provided on the pin 358 to mesh with corresponding gear teeth formed on the inner periphery of the sleeve hub 354 to provide a spline engagement therewith, and extend rearwardly into mesh with the teeth of the disk gear 350. With this construction it will readily be seen that a fine adjustment in the relative position of the hand wheel 344 to the disk gear 350 and hand wheel shaft 342, may be obtained by rotating the graduated disk 352 through any predetermined amount. The graduated disk 352 is maintained in predetermined angular position to lock the disk gear 350 and hand wheel shaft 342 in fixed relation to the hand wheel 344 by means of a spring-pressed plunger 364 which is carried in a boss 366 on the graduated disk, and is arranged at its rear end to engage in any one of a number of holes formed in a disk 368 rigidly secured to the hand wheel 344. In order to permit the hand wheel 344 to be moved freely with relation to the disk gear 350 and hand wheel shaft 342 to secure

a rough adjustment thereof, the pin 358 may be moved axially to disengage the gear teeth 362 from the teeth of the disk gear 350. A spring-pressed detent 370 supported on the vernier disk 5 352, is arranged to engage alternatively with two recesses formed in the pin 358 to maintain the pin alternatively in its engaging or disengaged position.

A power cross feed for the machine, is obtained by means of a power cross feed mechanism which comprises a ratchet and pawl mechanism adapted for imparting a step-by-step advancing movement to the hand wheel 344 (see Figs. 12, 14 and 15). This mechanism comprises 10 a ratchet 374 provided on the external periphery of the hand wheel 344 for engagement by a pawl 376 adjustably mounted on a pawl lever 378 which is pivotally mounted on a carrier arm 380 pivoted at 382 on the machine frame. A tension spring 384 connected between a point on the pawl lever 378 and a lug 386 on the link 396 hereinafter described, tends normally to maintain the pawl in engagement with the ratchet. Reciprocatory movements are imparted to the carrier lever 380 15 and pawl 376 by means of a crank shaft 388 supported in the machine frame parallel to the control shaft 286 above described. The crank comprises a pivot block 390 adjustably supported in guideways 392 in a disk 394 on the forward 20 end of the crank shaft 388, and is connected by an upwardly extending link 396 to the carrier lever 380. In order to vary the amount of reciprocation of the feed pawl 376 and thus to control the rate of feed, the block 390 is adjustably 25 positioned in the guideway 392 toward or away from the axis of rotation of the crank 388 by means of an adjusting screw 398 which is rotatably mounted in a bracket 400 mounted across the end of the guideway, and screw-threaded into 30 the carrier block 390.

With the present construction, driving connections are provided for driving the crank shaft alternatively from the table motor to impart a continuous reciprocatory movement to the pawl 45 for a continuous cross feed, or from the reversing lever to provide an intermittent cross feed.

The driving connections for the feed crank shaft 388 include a clutch element 402 rigidly secured to a shaft 404 which is in axial alignment with the feed crank shaft 388, and is connected to turn with and for axial movement relatively thereto by means of a loose coupling 406. At its rear end the shaft 404 is supported within a sleeve member 408 which is externally supported in a bearing 410, and has formed thereon a clutch face 412 for engagement with the clutch 402. At its forward end the shaft 404 is supported within a sleeve member 414 which is externally supported in a bearing 416 in the machine frame, and is provided with a single tooth clutch member 418 arranged for engagement with the corresponding element on the clutch member 402.

The sleeve member 408 is continuously driven from the table motor 132 to impart a continuous rotary movement to the crank shaft 388 through the clutch 402 by means of connections which include a shaft 422 (see Figs. 7, 8 and 12) provided at one end with a bevel gear 424 arranged to mesh with a bevel gear 426 carried on the shaft 140 driven from the table motor 132, and at its other end with a spiral gear 428 which meshes with a corresponding spiral gear 430 formed on the sleeve member 408.

An intermittent drive is imparted to the feed crank shaft 388 in timed relation to the table re-

ciprocation through driving connections from the reversing lever 266, which are arranged to impart an oscillatory movement to the sleeve member 414 through a complete revolution successively in opposite directions upon each reversal in the position of the reversing lever. These connections (see Figs. 12 and 13) comprise a gear 432 on the sleeve 414 meshing with a gear 434 which is keyed to the control shaft 286, and has formed thereon a dwell surface extending substantially half way round its periphery. The proportions of the gear 432 and the dwell gear 434 are such that the rotational movement imparted to the gear 434 through the major portion of one revolution upon each reversal in the position of the reversing lever 266, causes the gear 432 and sleeve member 414 to be rotated through exactly one revolution regardless of any variations in the angular movement of the shaft 286 with the reversing lever 266. In order to provide a positive stop for the gear 432 and sleeve member 414 at the end of one complete revolution in either direction, a semi-circular segment 436 is formed integrally with the dwell surface of the gear 432 and adjacent thereto, to engage in a corresponding concave segment 438 of a disk 440 carried on the sleeve member 414 adjacent the gear 432. This mechanism for imparting a rotational movement to the crank shaft 388 through exactly one revolution with each shift in the position of the reversing lever 266 regardless of variations in the throw of the lever, forms no part of the present invention, but is illustrated and claimed in United States Patent No. 2,079,007, dated May 4, 1937, which issued from application for Letters Patent 35 in the United States Patent Office, Serial No. 49,723, filed of even date herewith, in the name of Walter A. Gigger.

The clutch member 402 may be shifted manually to the left (see Fig. 12) into engagement with the clutch face 412 to secure a continuous automatic feed, or to the right into engagement with the single tooth clutch face 418 to secure an intermittent power cross feed, by means of connections which include a clutch control shaft 442 which extends parallel to the feed crank shaft 388, and is loosely mounted for axial and rotational movement in bearings 444 and 446 formed in the machine frame. A clutch shifting yoke 448 rigidly secured to the clutch shaft 442 is arranged to engage in a peripheral groove 450 formed in the clutch member 402. A compression spring 452 coiled about the control shaft 442 between the bearing 444 and the clutch shifting yoke 448, tends normally to maintain the clutch shaft 442 and yoke 448 in an advanced position with the clutch member 402 in engagement with the single tooth clutch member 418 for the intermittent power feed. The position of the clutch shaft 442 and yoke 448 may be controlled manually to shift the clutch from intermittent to continuous feed position by means of a clutch control rod 454 which is provided at its outer end with a knob 456, and is supported in a bearing 458 in the machine in axial alignment with and abutting the clutch shaft 442. A cross pin 459 secured to the control rod 454 is arranged to slide in a slot 462 formed in an extension of the bearing 458 for the forward position of the control rod 454, and is arranged when the control rod 454 is pushed rearwardly in shifting the clutch against the pressure of the spring 452, and rotated to engage in locking position against an end portion of the bearing 458 to lock the clutch in continuous cross feed driving position.

In accordance with the present invention, the cross feed hand wheel unit including the ratchet and pawl mechanism are constructed and arranged to secure an extremely fine adjustment of the power depth feed which may be to any desired fraction of a tooth of the ratchet. To this end a bare spot 460 is provided on the ratchet 374 (see Figs. 14, 17 and 18), so that the feeding movement of the hand wheel will be arrested always at exactly the same angular position when the reciprocating pawl rides onto the plain or bare surface 460 of the ratchet. It will readily be seen that an additional increment of feed of any desired amount regardless of the length of each advancing movement imparted to the hand wheel by the reciprocating pawl may be obtained by manipulating the vernier disk 352 to move the hand wheel in a reverse or clockwise direction the desired amount with relation to the hand wheel shaft 342 and disk gear 350.

The power cross feed pawl 376 may be manually thrown into and out of operation by means of a hand lever 463 which is pivotally supported on a pivot pin 464 on the machine frame, and carries a cam roll 466 which is arranged when the hand lever is raised to engage with and move the pawl 376 out of engagement with the ratchet against the pressure of the spring 384. Downward movement of the lever is limited by the engagement of a fixed pin 468 with a recess 470 formed in the under side of the hand lever 463. There is also provided adjacent the hub portion of the hand lever 463, a V-shaped projection 472 which is arranged to be engaged by a spring-pressed detent 474 to maintain the hand lever yieldingly in either of its alternative operative and inoperative positions.

Further in accordance with the present invention, a novel control device is provided which forms a part of the cross feed hand wheel mechanism above described, and has for one object to modify and improve the operation of the hand wheel unit during manual operation of the cross feed, and for another object to permit automatic control from the hand wheel when so desired, of certain of the operating units of the machine to produce a more unified and fully automatic operation of the machine for a performance of certain operating cycles. The control mechanism referred to, comprises a vertically movable hand wheel control slide 480 which is supported in ways 482 on a stationary portion of the machine directly behind the hand wheel, and has formed therein a longitudinally extending slot 484 to receive the sleeve hub of the disk gear 350. Associated with the slide 480 is a stop switch which comprises a vertically movable switch plunger 486 and a switch contactor 488 which operates to close the switch contact 3-35 forming part of the electrical control system of the machine hereinafter described. A light compression spring coiled about the plunger between a collar formed on the upper end thereof and the switch supporting bracket, tends to raise the plunger and switch contactor 488 to closed position. The switch is controlled from the slide by means of a pivotally supported switch lever arm 490 which at one end is arranged to bear against the upper end of the plunger 486 and at its other end is arranged to engage within an aperture 492 in the slide 480. The slide is normally held in a raised position and the switch is held in a corresponding open position by means of a compression spring 494 which is seated at one end within a recess formed in the lower

end of the plunger, and at its other end against a stationary pin 496. Cooperating with the slide 480 is a stop pin 502 which is permanently secured to the rear side of the cross feed hand wheel 344, and is arranged for engagement with a right angle stop surface or recess 504 in the upper end of the slide 480 to provide a positive stop to the further advance of the hand wheel and grinding wheel carriage controlled thereby. The stop position of the hand wheel determined by the engagement of the stop pin 502 with the stop surface 504 is arranged to coincide exactly with the stop position of the hand wheel determined by the bare spot 460 of the ratchet, so that there can be no possibility of interference and possible injury to the machine parts. There is also provided with the present construction, a second somewhat longer backing-off stop pin 506 which may be located in any one of seven holes 508 formed on the back side of the hand wheel 344, and serves as an adjustable stop to limit the backing off movement of the cross feed hand wheel in moving the grinding wheel away from the work. The backing-off stop pin is arranged during the backing-off movement of the hand wheel in a clockwise direction when viewed from the front of the machine, to engage with a cam surface 510 formed on the upper end of the slide 480, and operates first to depress the slide against the pressure of the spring 494 to close the automatic hand wheel control switch contact 3-35, and thereafter to engage against a vertically extending stop portion of the surface 510 to prevent further backing-off movement of the hand wheel. There is also provided on the opposite side of the slide 480, a cam surface 512 which serves as a safety device to enable the adjustable backing-off stop pin 506 to ride over the top of the slide without engaging the stop surface 504 in case the pin 506 is located in such a position on the hand wheel as to engage therewith during power feeding movement of the hand wheel prior to the engagement of the pawl 376 with the bare spot 460.

From the foregoing description of the control devices including the slide 480 and pin 502, it will readily be seen that this device is of material assistance to the operator in the manual operation of the cross feed hand wheel, both to bring the work exactly to the desired depth, and also to provide a definite stop position to which the hand wheel may be retracted in backing off the grinding wheel. It will be noted that with the construction above set forth, the adjustment of the hand wheel mechanism for manual operation to the exact depth of feed required, is performed in an identical manner as for the power cross feed previously described.

In accordance with one feature of the invention, the control device above described is arranged in connection with the electrical control system of the machine, so that the opening of the switch contact 3-35 as the cross feed hand wheel is advanced from its fully retracted position, will operate to disable the cross feed rapid movement to advance the grinding wheel, and that this control is re-established only upon closing of the contact 3-35 when the hand wheel is returned to its fully retracted position. The cross feed rapid movement cannot then be rendered operative after the grinding wheel has been partially or fully advanced to move the wheel spindle carriage and grinding wheel into interfering engagement with an unfinished work piece.

When desired, the control slide 480 may be

5 moved positively downward to an inoperative position by means of a hand lever 514 to permit the free movement of the hand wheel by the operator. The hand lever 514 is secured to a small pivot shaft 516 which is journalled in a bearing formed in a fixed portion of the machine, and carries a cam-shaped actuating disk 518 for engagement with a pin 520 on the back side of the slide 480. The movement of the hand lever 514 10 and disk 518 connected thereto in a counter-clockwise direction viewed from the front of the machine, acts to force the disk 518 and slide downward to inoperative position against the pressure of its spring 494. It may be noted that 15 the movement of the slide to inoperative position serves simultaneously to close the switch contact 3-35 so that the cross feed rapid movement will be rendered available at all times either to retract or advance the wheel spindle carriage at the rapid rate.

20 In accordance with another feature of the invention, the control device above described, is arranged in connection with the electrical control system hereinafter set forth, to secure an automatic operation of the machine for the performance of a series of identical grinding operations to be performed on work pieces successively placed in the machine. To this end, electrical connections are provided which are 25 rendered operative by the movement of the control knob 850 to the hand wheel position shown in Fig. 33, and are controlled by means of the cross feed hand wheel operating through the switch contact 3-35. These connections as 30 hereinafter more fully set forth, are rendered operative by the opening of the switch contact 3-35 to start the table and headstock motors, to turn on the supply of coolant, and to render the cross feed rapid movement operative to advance the wheel spindle carriage, and which are 35 further actuated by the closing of the switch contact 3-35 to stop said motors, to turn off the supply of coolant, and to render the cross feed rapid movement operative to retract the 40 wheel spindle carriage.

45 The construction and arrangement of the electrical controls to set up the machine for automatic hand wheel operation will be set forth in connection with the description of the electrical control system. The mode of operation obtained thereby may be briefly described as follows:—If it be assumed that the cross feed to depth has taken place, the cross feed pawl is reciprocating but is ineffective to further advance the hand wheel due to the engagement of the pawl with the bare spot 460, the headstock is rotating, coolant is being supplied to the point of grinding contact, the table motor is running, and the table may be reciprocating 50 back and forth depending upon the position of the power hand wheel clutch above described. The operator now raises the hand lever 463 to disengage the pawl 376 from the ratchet, and turns the cross feed hand wheel backward to back off the wheel. This backing-off movement is continued until the backing-off pin 506 engages with the cam surface 510, causing the control slide 484 to be depressed, and thus closing the switch contacts 3-35. Electrical connections 55 are thereby rendered operative as hereinafter more fully to be described in connection with the electrical control system for the machine to stop the headstock, the supply of coolant, the table motor, the pawl 376, and simultaneously 60 to render the cross feed rapid movement herein-

65 after described operative to move the grinding wheel carriage rapidly away from the work. The machine is now in position for the substitution of a new work piece in the machine by the operator. In order to start the machine again in operation, the cross feed hand wheel is advanced slightly to move the backing-off pin 506 out of engagement with the cam surface 510, permitting the slide 484 to rise under the pressure of its spring 498 to disengage the switch contacts 10 3-35. The opening of this switch operates to again start the rotation of the head stock, to turn on the supply of coolant, to start the table motor and the reciprocation of the pawl 376, and simultaneously renders the cross feed rapid 15 movement operative to advance the carriage toward the work. The operator now moves the hand lever 463 downwardly to permit the engagement of the pawl 376 with the ratchet 314, so that the cross feed hand wheel will be advanced to depth by the power reciprocation of the pawl 376, thus completing the cycle of operations.

20 In accordance with certain features of the invention, a novel and improved mechanism is 25 provided for imparting a rapid movement to the wheel spindle carriage towards and away from the work. With the construction herein disclosed, the rapid movement of the grinding wheel is effected by means of mechanism including a 30 constant throw, crank actuated, shifting lever which operates to shift the feed screw 332 axially between two exactly determined positions, so that no further change or adjustment of the cross feed mechanism may be required when for any 35 reason the rapid movement is employed to back off the grinding wheel, and thereafter to return the same to operating position. As best shown in Figs. 20 to 23 inclusive, the shifting mechanism comprises a crank shaft 522 having formed thereon a crank pin 524 offset from the shaft, which is connected by means of a short link 526 to two downwardly extending arms of a 40 crank actuated shift lever 528 carried on a pivot shaft 530. The upper end of the shift lever 45 528 takes the form of a yoke which carries two cam rolls 532 arranged to engage in a peripheral groove 534 formed in a sleeve member 536 which is in turn carried on a sleeve 538 adjacent one 50 end of the feed screw shaft 332, and forms a 55 movable connection between the shift lever 528 and the sleeve 538. In order to permit the feed screw to turn freely with relation to the supporting sleeve member 538, and at the same time to prevent any relative axial movement thereof, 60 the sleeve member 538 carries on the internal periphery thereof, bushings 540 and 542 to receive the feed screw shaft, and is prevented from axial movement with relation to the feed screw by means of end thrust bearings which are supported respectively against the flange 348 and a 65 nut 544 screw-threaded to one end of the feed screw shaft. The assembly including the feed screw 332 and sleeve 538 are externally supported in two bearings 546 and 548 formed in opposite 70 sides of a casing 549 within which the entire mechanism for axially shifting the feed screw is housed. A key 551 supported within the bearing 546 as shown in dotted lines in Fig. 23, engages in a corresponding keyway or slot in the periphery of the sleeve 538 to prevent rotational 75 movement of the sleeve. The movement of the feed screw shaft 332 and sleeve 538 in a forward direction is limited by the engagement of a flange or rib 550 on the sleeve 538 with a stop surface 75

552 formed on the inner face of the bearing 548. The movement of the feed screw shaft 332 and sleeve 538 in a rearward direction is similarly limited by the engagement of a flange which 5 takes the form of a collar 554 rigidly secured to the sleeve 538 with a corresponding stop surface 556 formed on the inner face of the bearing 548.

The throw of the crank lever 528 is adjusted 10 with relation to the length of travel of the feed screw 332 and sleeve 538 between the two limiting positions above described, so that 180° rotation of the cam shaft 522 will operate to move the feed screw and sleeve 538 from one to the other of said 15 limiting positions with the rib 550 or collar 554 in engagement with the corresponding abutment. In order to make allowance for the overtravel of the crank shaft in reaching the stop position, and at the same time to maintain the feed screw 332 20 and sleeve 538 always in exactly one or the other of said limiting positions, a yielding connection is provided between the sleeve member 536 directly connected as above pointed out, to the crank 522, and the sleeve 538 which controls the 25 position of the feed screw 332. To this end, a series of compression springs 558 are supported in recesses formed respectively in each end of the sleeve member 536, and in corresponding recesses formed in two collars 560 and 562 inserted at each end of the sleeve member 536 to 30 engage respectively with the adjacent face of the rib 550 and of the collar 554. In order to maintain a constant relative angular position between the collars 560 and 562 and the sleeve member 536, there are also provided at spaced intervals 35 around the said collars, locating pins 564 which are arranged to extend through corresponding recesses formed in the end portion of the sleeve member 536. It will be noted that each of these 40 pins is provided at its outer end with an enlarged head which fits into an enlarged portion of the corresponding recess in the sleeve member 536, to limit the amount of the separation between the sleeve 536 and each of the collars 560 45 and 562 under the pressure of the springs 558 so that an initial compression of the springs is maintained which is sufficient to successfully hold the cross feed screw from movement under any load which would normally be encountered during truing or grinding operations. With the construction and arrangement of parts above described, the movement of the screw shifting lever 528 to its forward limiting position, for example, causes the rib 550 to be brought into engagement 50 with the abutment 552, and thereafter causes the springs 558 to be compressed, so that the collar 560 is positively engaged on one side by the rib 550, and on the other side by the springs 558 compressed by the movement of the supporting 55 sleeve 536 and crank lever 528 to lock the feed screw 332 and wheel spindle carriage controlled thereby exactly in the desired position. The springs 558 operate as a cushioning or take-up device to maintain the feed screw 332 accurately 60 and certain in its fully advanced or retracted position regardless of any slight variations in the operation of the motor and braking device hereinafter described to stop the crank shaft 522, which might cause the shift lever 528 to be 65 stopped either before or after reaching the limit of its throw.

A specific advantage of the crank construction above described for effecting a rapid movement of the wheel spindle carriage toward and away 70 from the work, in which the crank is stopped at

the limit of its throw in each direction substantially in dead center position with relation to the oscillatory driving member 528 and connecting link 526, is found in the fact that the crank motion provides a most efficient pick-up and slow 5 down in the movement of the wheel spindle carriage from one limiting position to the other. This construction is also of advantage to facilitate the starting and stopping of the crank shaft 522 which takes place at alternative angular 10 positions of the shaft at which the inertia of the heavy wheel spindle carriage 112 has been substantially dissipated through the operation of the crank motion in slowing the carriage to a stop.

Another feature of the invention consists in 15 the construction and arrangement of the feed screw shifting and supporting mechanism which will permit of adequate lubrication of the several bearing surfaces, necessarily tight fitted to secure the required degree of accuracy, and at the same 20 time will prevent possible accumulation of dust or grit particularly between the flanges 550 and 554 and the contacting surfaces 552 and 556 which would seriously affect the operation of the machine. For the protection of these parts and 25 also to provide a chamber or well to collect lubricant, the screw shifting mechanism is entirely 30 enclosed within the casing 549, as best shown in Fig. 23. Lubricant is supplied under pressure to the several bearing surfaces through a feed line 35 565 including a pipe 566 which is supported on the casing 549 in axial alignment with the feed screw 332 to engage within an axial bore 567 in the feed screw, thus forming an extensible connection to the bore 567. Oil passes freely from 40 the bore 567 through a duct 568 and through a space provided between the surface of the feed screw 332 and the internal surface of the sleeve 538 to the bushings 540 and 542 and end thrust 45 bearings for the sleeve 538. Oil is supplied to the 50 bearings 546 and 548 through a number of wood filters 569 which extend radially through the sleeve 538, three being provided at spaced distances about the periphery of the sleeve for the lubrication of each bearing, so that a limited 45 amount of lubricant which is wholly free from grit or other foreign substances is supplied to each bearing and to the stop surfaces 552 and 556 for determining the axial position of the feed screw 332.

The rotation of the crank shaft 522 is controlled by means of an electric motor 510 through driving connections which include a drive shaft 572 in axial alignment with and keyed to turn with the armature shaft 574 of the motor. A 55 worm 576 on the drive shaft meshes with a worm gear 578 secured to one end of the crank shaft 522. There is also provided with the motor, a mechanical multiple disk brake (see Figs. 24 and 25) which comprises a brake member 580 splined 60 to the lower end of the armature shaft 574 between a braking surface 582 formed rigidly with the motor casing, and an axially movable braking member 584 which is provided on its external periphery with gear teeth arranged to engage with 65 an internal gear member 586 on the casing, to prevent rotational movement of the member 584. A brake lever 590 is supported on the casing coaxially with the armature shaft 574, and is provided on the hub portion thereof with a cam 70 surface 592 which is rendered operative by the rotation of the brake lever to engage with a corresponding cam surface on the movable member 584 to move the member 584 into braking engagement with the braking member 580 and 75

the member 580 into engagement with the surface 582. A tension spring 594 tends normally to hold the brake lever in braking position. The brake lever is moved in an opposite direction to release the brake by means of a solenoid 596 provided with an armature 598 connected by means of a link 600 to the brake lever 580. The solenoid is electrically connected to the motor so that the starting of the motor operates to energize the solenoid to release the brake, and the de-energizing of the motor operates simultaneously to de-energize the solenoid and to permit the setting of the brake under the influence of its spring 594.

For controlling the operation of the cross feed rapid movement, electrical connections are provided which may be operated either manually or automatically to start the motor 570 and to release the brake, and operate automatically thereafter to stop the motor and set the brake, and thus to stop the crank shaft 522 at the end of each successive half revolution of the crank 522. The starting controls include the hand wheel switch 488 and a rapid movement control knob 800, either of which may be operated as more fully set forth in connection with the electrical control system hereinafter to be described, to start the motor 570. The motor is then automatically stopped and the brake is set by means of a stopping switch (see Figs. 21 and 22) comprising a switch plunger 602 which carries switch arms 604 and 606 which are alternatively operable to close the contacts 31—32 and contacts 30—32. As more fully set forth in the following description of the electrical control system, the movement of the switch plunger 602 in either direction to move one of the switch arms 604 and 606 to open position and to close the other, operates to disconnect the motor 570 and set the brake. The operation of the switch plunger 602 is controlled from the crank shaft 522 by means of a split cam (see Figs. 20 to 22 inclusive) comprising disks 608 and 610 pinned together in adjusted position on the crank shaft 522, and arranged to be engaged by a cam lever 612 pivoted at 614 on the machine frame and provided with a cam follower roll 616. An abutment 618 on the cam lever 612, engages the end of the switch plunger 602 which is held in engagement therewith by means of a compression spring 620 coiled about the plunger between a collar on the end thereof and an abutting portion of the switch bracket. A tension spring 622 connected at one end to the cam lever 612 and at its other end to the frame, tends to maintain the follower roll 616 in engagement with the periphery of the split cam 608, 610.

With the construction and arrangement of the mechanism above described, for stopping the motor 570 and applying the brake to arrest the rotation of the crank shaft 522 in either of two predetermined positions corresponding to a fully retracted or advanced position of the wheel spindle carriage as the case may be, it has been found necessary to provide an adjustment in the device for controlling the operation of the stopping switch from the crank shaft 522, in order to make allowances for delay in the operation of the stopping device to stop the crank shaft after the switch has been shifted to stop the motor and apply the brake. In accordance with the present invention, this adjustment is made for each individual machine by an adjustment of the relative positions of the two disks 608 and 610 of the split cam. The angular position of the disk 608 is adjusted so that the drop portion of the disk 608 may occupy the correct angular position with

relation to the crank shaft 522 to cause the switch to be shifted as shown in Fig. 21 to close the contacts 31—32 and open the contacts 30—32 to stop the crank shaft with the wheel spindle carriage in its fully advanced position. Similarly, the position of the rise portion of the cam on the disk 610 is adjusted angularly on the crank shaft 522 to cause the shifting of the switch to close the contacts 30—32 and to open the contacts 31—32 and to stop the crank shaft 522 with the wheel spindle slide in its fully retracted position as best indicated in Fig. 22. For the convenience of the operator to ascertain whether the crank shaft 522 is being stopped in the correct angular position, an indicator device is provided which comprises a marker 624 on a stationary portion of the machine, and two indicators 626 cooperating therewith on opposite sides of a bevelled plate member 628 rigidly secured with the cams 608, 610 on the crank shaft 522, each of said indicators including a center line marked c and an additional line at each side thereof to indicate the limits of permissible variation in the two stop positions of the crank shaft.

Coolant is supplied to the point of grinding contact by means of a coolant system which includes a coolant water tank 630 located to the side of the machine, a water pump of ordinary description indicated at 632, an alternating current motor 634 for driving the pump, and a pipe line 636 through which coolant is passed to a nozzle 638. There is provided in the pipe line a manually operable cock 640, and a coolant supply valve 642 which is controlled by means of a solenoid 644 to turn on and shut off the supply of coolant (see Figs. 2, 3 and 4). The valve 642 comprises a casing within which is mounted a valve plunger 646 (see Fig. 3) provided at its upper end with a valve member 648 which engages against a valve seat 650 formed in the outlet port of the valve. A compression spring 652, coiled about the plunger 646 and a sleeve portion of the casing within which the plunger is mounted to move, acts against the valve member 648 to maintain the valve normally in closed position to arrest the flow of coolant. In order to form a watertight connection and to prevent contact by the coolant with the spring 652, a flexible bellows 653 is provided secured at its upper end to the valve member 648 and at its lower end to the valve casing. The valve is moved to open position against the pressure of its spring 652 by means of an actuating lever 654 pivoted at 656 on the valve casing, and connected at one end to the lower end of the plunger 646 and at its other end through a link 658 to a solenoid armature 660. A stop pin 662 screw-threaded to the end of the lever 654, is arranged for engagement with the valve casing to limit the upward movement of the plunger in seating the valve. The electrical connections for controlling the operation of the solenoid to turn on and shut off the supply of coolant, will be hereinafter more fully described in connection with the electrical control system for the machine.

Lubricant is supplied to the various parts of the machine from a lubricating oil tank 664 in the base of the machine, by means of a lubricant pump 666 which is continuously driven during the operation of the machine, by means of an alternating current motor 668.

With the present construction, the grinding wheel 669 is carried on a spindle 670 which is mounted for rotational and axial movements in bearings 671 and 672 on the wheel spindle car-

riage 112. Rotational movements are imparted to the spindle from an electric motor, generally indicated at 673 in Figs. 1 and 26, through a belt and pulley drive which includes a series of belts 5 674 arranged to ride in grooves formed respectively in a pulley 675 carried on one end of the spindle 670 and in a corresponding pulley 675a carried on the armature shaft of the motor 673.

For imparting axial movements to the spindle 10 there is provided a reciprocating member 676 which comprises a sleeve portion supported on a vertical pivot shaft 677, and two parallel arms extending therefrom which are connected by means of pins 678 to a ring or collar 679 which is 15 loosely sleeved on the spindle 670 to engage against an abutting portion of a sleeve member 680 frozen onto the spindle. There is also formed integrally with the sleeve portion 676, a cam lever arm 681 which is provided at its tip 20 with a bearing surface to engage with an actuating cam 682, so that as the lever arm rides from the low onto the high portion of the cam, a driving impulse is imparted to the spindle in an axial direction to the left as shown in dot-and-dash 25 lines in Fig. 29. A heavy compression spring 683 coiled about the spindle, operates as a return spring. The spring 683 is supported at one end against a shoulder formed on a collar 684 which is in turn supported against an adjacent portion of the stationary bearing 671, and at its other end engages a corresponding shoulder formed on a sleeve member 685 secured to move axially with the spindle 670 so that the spindle 670 is forced axially to the right, as viewed 30 in Figs. 26, 27 and 29, to maintain the sleeve member 680 in engagement with the ring 679 and the cam lever in engagement with the actuating cam 682.

The cam 682 is driven at a relatively slow rate 40 from the rapidly rotating spindle through connections which comprise a vertically arranged drive shaft 686 supported at its upper end in a ball bearing 687 and at its lower end in a bearing 688 on the wheel spindle carriage 112. The shaft 686 is continuously driven from the spindle by means of a worm gear 689 rigidly secured to the shaft and a driving worm 690 which is sleeved into the spindle 670. The worm 690 and sleeve member 685 are splined to turn with the spindle 50 by means of pins 691 supported respectively on the sleeve member 680 frozen to the spindle as above pointed out, and on the sleeve member 685, which engage respectively in slots formed in the adjoining ends of the worm 690. The collar 684 is splined to the sleeve 685 by the engagement 55 of a tongue formed on the collar with a corresponding slot in the sleeve 685.

The cam 682 forms part of a sleeve member 692 which is loosely mounted on the continuously 60 driven shaft 686, and is arranged to be connected thereto by means of a spindle reciprocating starting and stopping clutch. The sleeve member 692 is keyed to a sleeve bushing 693 loosely mounted for rotational and axial movements with relation 65 to the shaft 686, and has formed on the lower end thereof a clutch member 694 adapted for engagement with a corresponding clutch member formed on the upper face of the worm gear member 689. Two compression springs 695 seated within recesses formed in the cam sleeve 692, and arranged at their upper end to engage with a ring 696 supported against the flanged upper end of the sleeve bushing 693, and against the lower 70 end of a supporting collar 697 for the shaft bear-

ing 681, act normally to force the cam sleeve 692 downwardly to engage the clutch.

With the present construction, mechanism is provided which acts when rendered operative, to disengage the clutch and to stop the rotation of the actuating cam 682 in a predetermined angular position, so that the spindle and the grinding wheel carried thereby will be maintained in a fully retracted position in which the spindle may receive a maximum amount of support from the spindle bearing 671. The mechanism for disengaging the clutch specifically comprises a clutch lever 699 which is rigidly secured to a vertically extending rock shaft 700 and is provided with a clutch pin 701 arranged to engage with a clutch face cam 702 formed on the cam sleeve member 692 directly beneath the cam 682. In operation the actuation of the clutch lever 699 and pin 701 causes the pin to move against the cam sleeve 692, and thereafter into engagement with the low portion of the cam surface 702 when this low portion of the cam comes opposite the pin, thus permitting the final movement of the pin and lever into operating position. The continued rotation of the cam sleeve 692 now causes the pin 701 to ride against the high portion of the cam 702 so that the sleeve 692 is raised to disengage the clutch.

In order to provide a definite stop position for the cam sleeve 692 and cam 682 which will correspond to a fully retracted position of the spindle 670, the cam 702 is provided with a stop surface 703 which engages with the pin to provide a positive stop against further movement of the cam 682. There is also provided on the peripheral surface of the cam sleeve 692, a recess 704 which is arranged to be engaged by a correspondingly tapered tip portion of the pin 701 to lock the cam yielding in desired stop position. In starting the spindle reciprocation, the cam 40 lever 699 and pin 701 are moved out of engagement with the face cam 702 so that the cam sleeve 692 is permitted to move downwardly under the pressure of the springs 695 to engage the clutch.

The specific mechanism above described for starting and stopping spindle reciprocation, forms the subject-matter of an application for Letters Patent filed of even date herewith in the name of Allan C. Abrams, Serial No. 49,730, and no claim is made therefor as part of the present invention, except so far as this mechanism is identified with the present applicants' automatic control system for a grinding machine.

The mechanism disclosed for starting and stopping spindle reciprocation, is arranged to be controlled automatically from applicants' electrical control system in combination with other operating units of the machine in setting up the 60 machine for the performance of certain operating cycles, and more particularly for true grinding, as hereinafter described. A preferred form of automatic control for controlling the position of the spindle reciprocating clutch, comprises a 65 solenoid 705 mounted in a casing 706 on the spindle carriage 112 directly above the spindle 670. The solenoid armature generally indicated at 707 is connected by means of a short link 708 to one end of a vertically extending lever arm 709 which is secured at its lower end to a pivot 710 on the spindle carriage. The lever 709 is also provided with a bearing surface 711 which is arranged for engagement with one end of an axially movable control rod 712 provided with a 75

cylindrical rack 713 meshing with a gear segment formed on a lever arm 714 secured to the rock shaft 700. The control rod 712 is normally moved to the right as viewed in dot-and-dash lines in Fig. 31 to disengage the clutch by means of a compression spring 715 coiled about a reduced portion of the control rod 712 between a shoulder formed thereon and a nut 716 which is recessed to provide a bearing for one end of the rod 712. The energizing of the solenoid causes the solenoid armature 107 to be moved to the left to the position shown in Figs. 29 and 31, so that the lever 709 engages with and forces the control rod 712 to the left against the pressure of the spring 715, to move the clutch lever 699 and pin 701 out of engagement with the clutch cam 702 to permit the engagement of the clutch. When the solenoid is again de-energized, the control rod 712 is permitted to move to the right under the pressure of its spring 715, causing the lever 709 to move to the dot-and-dash position shown in Fig. 31, while the clutch lever 699 and pin 701 are moved into the path of the cam 702 to again disengage the clutch and stop the spindle reciprocation.

In accordance with the present invention, an electrical control system is provided for the machine, which enables the operator quickly and conveniently to control the operation of the several cooperating units in accordance with a number of operating cycles necessary for the performance of different classes of work on the machine. The control system includes a number of manually operable switching elements for controlling severally or collectively the several operating units, together with a number of control devices which are particularly adapted to prevent operation of any one or more of the several units in a manner inconsistent with the particular cycle of operations for which the machine is set up, and thus to prevent possible injury to work or machine parts.

The electrical driving units comprise several alternating current motors including the main grinding wheel spindle motor 673, the coolant pump motor 634, the lubricant pump motor 668, the cross feed rapid movement motor 570, and a generator motor 730 which is in turn directly connected to drive a headstock motor generator 731 and a table motor generator 732. The headstock generator is a constant potential self-excited generator which supplies the necessary power for running the headstock motor 118, and also supplies current to the direct current control circuit hereinafter to be described, and to the fields of all of the direct current motors and generators above mentioned.

The several manually operable controls for the machine are mounted on a control panel 733 which is mounted on the front side of the machine beneath the table. These controls include a machine start button 734 and a stop button 735 which operate to control the starting and stopping of the main spindle driving motor 673, the generator motor 730, the oil pump motor 668, and the coolant pump motor 634. The pushing of the start button 734, as best shown in the electrical diagram illustrated in Figs. 47 and 48, and in the explanatory diagram Fig. 49, operates to close the contacts 75-83 to energize the starting switch solenoid 736, which in turn operates to close the main line contacts 75-87, 76-98 and 77-85, and also a holding switch contact 75-84. The 75 pressing of stop button 735 operates to open the

contact 82-83 to de-energize the main switch solenoid 736, and thus to stop the machine.

The starting of the generator motor 730 and headstock generator 731 operates immediately to supply current to the entire direct current control circuit which, as best shown in the explanatory diagram Fig. 50, comprises a supply line 1, 3 and a return line 2, 4. The headstock motor armature designated at 731 and the headstock motor shunt field 738 are connected across the supply and return wires 1, 2. In order to permit variations in the motor speed, a headstock field rheostat HR is provided in series with the shunt field 738. This rheostat is controlled by means of a knob 739 on the left side of the panel 733 to determine the driving rate of the head stock motor.

In accordance with one feature of the present invention, there is provided on the control panel 733, a headstock control knob 740 which is rotatable in a clockwise direction to start the headstock in operation, and also to start the supply of coolant, and rotatable in an opposite direction to stop the head stock and shut off the supply of coolant. The headstock knob may also be depressed against the pressure of a spring to jog 25 the headstock motor at a slow rate. As best shown in Figs. 33 to 36 inclusive, and 38, the headstock knob 740 is secured to the upper end of a rotatable and axially movable switch control rod 741 which is held normally in a raised rest position by means of a compression spring 742 which is coiled about the control rod 741, and is seated at one end within a recess formed within the headstock knob 740, and at its other end within a recess formed in the panel casing 733. 30 There are rigidly secured to the control rod 741, a starting switch actuating arm 743 and a stop switch control arm 744. The headstock starting switch comprises a plunger 745 which carries two switch arms 746 and 747, and is normally held in 40 rest position to the left in engagement with the lever arm 743, as shown in Fig. 33, by means of a compression spring 748, in which position the switch arm 746 engages the contacts 44-50. The stop switch similarly comprises a switch plunger 45 749 having mounted thereon switch arms 750 and 751, and is provided at one end with an enlarged head which engages with a forked portion of the switch lever arm 744. A compression spring 752 tends normally to move the plunger to the right, 50 as shown in Fig. 33, so that the switch arm 751 is normally positioned to close the contact 43-44. The jog switch comprises a switch plunger 753 which carries switch arms 754 and 755, and is arranged to engage against one arm of a small 55 bell-crank lever 756, the other arm of which engages the lower end of the headstock switch control rod 741. A compression spring 757 tends normally to maintain the switch plunger 753 to the left, as illustrated in Fig. 33, with the switch arm 754 in engagement with the contact 40-41.

The operations of the headstock motor and the coolant flow control valve 642 are controlled from the headstock knob 740 through the starting and stopping switches above described, by means of 65 a number of secondary switch connections including a head stock line and dynamic brake contactor LE, head stock accelerating relay 1A, a head stock accelerating contactor 2A, control relay CR, and coolant solenoid contactor CS. 70 These switches are all mounted on a panel 758 indicated in Fig. 1 and in the electrical diagram Fig. 47.

Assuming that the several controls of the machine hereinafter more fully to be described, are 75

set for grind position, knob control, and for headstock alone starting position, the turning of the headstock knob 740 in a clockwise direction causes the lever arm 743 to engage with and move the switch plunger 745 to the right to close the switch contacts 44—49—47, thus energizing coil CR. Contact CR 44—45 closes, energizing coil LE, contact CR 46—47 closes, forming a holding circuit as the headstock knob 740 is permitted to 5 turn to its normal position, and contact CR 9—10 closes, energizing coil 1A after the headstock motor is accelerated. Contact LE 3—6 closes, starting the headstock motor, and contact LE 9—11 opens, disconnecting the dynamic brake. Contact 1A 3—36 closes, energizing coil 2A. Contact 15 2A 3—5 opens, placing the field rheostat HR in the headstock motor field circuit, contact 2A 3—40 closes, energizing coil CS, thus starting the coolant running over the work, and contact 2A 20 7—9 closes, short-circuiting the armature accelerating resistor RI.

If it is now desired to stop the headstock, the rotation of the headstock knob in a counterclockwise direction causes the switch lever arm 744 to move the switch plunger 749 to the left to disengage the switch contact 43—44, thus de-energizing coils LE and CR. Contact CR 44—45 opens, keeping coil LE de-energized, contact CR 46—47 opens, keeping coil CR de-energized, 25 and contact CR 9—10 opens, de-energizing coil 1A. Contact LE 3—6 opens, stopping the headstock motor, and contact LE 9—11 closes forming a dynamic braking circuit which brings the motor to a quick stop. Contact 1A 3—36 opens, 30 de-energizing coil 2A, contact 2A 3—5 closes, short-circuiting the headstock field rheostat HR, and contact 2A 7—9 opens, placing the armature resistance in series with the armature 737, and 2A 3—40 opens, de-energizing coil CS to stop 35 the flow of coolant.

It will be noted that the headstock stop switch contact 43—44 is arranged so that the opening of the switch, addition to stopping the headstock motor by de-energizing coil CR, may also operate to de-energize coils UV and S controlling the 40 operation of the table, as hereinafter described, to stop the table.

Assuming that it is desired to jog or inch the headstock through a small angular distance in 45 setting up the work or for any other reason, the operator pushes downwardly upon the headstock knob 740, moving the switch control shaft 741 axially against the pressure of its spring 742 to move the jog switch plunger 753 to the right, 50 thus de-energizing the contacts 40—41 so that the coil CS is prevented from becoming energized to start a flow of coolant, and simultaneously closing contacts 44—45 to energize coil LE. Contact LE 3—6 closes starting the headstock motor, and 55 contact LE 9—11 opens disconnecting the dynamic braking resistor. The headstock accelerates only to a very slow speed which is maintained as long as the jog button is held down. When the knob is released, the motor stops immediately inasmuch as the switch plunger 753 is 60 then permitted to return again to the left to break the contacts 44—45 to de-energize the coil LE.

With the construction and arrangement of the 65 jog switch above described, it will readily be seen that the actuation of the jog switch by pushing downwardly upon the headstock button 740 may be employed at any time during the operation of the machine to arrest the flow of coolant, and 70 thus to permit the operator more readily to in-

spect the work, as, for instance, where the operator wishes to ascertain how closely the grinding wheel is approaching a shoulder on the work. Under these conditions, the operation of the jog switch will serve to de-energize the coil CS without otherwise interfering with the operation of the headstock motor. 5

In accordance with the present invention, there is provided on the control panel 733, a table control knob 759 which is rotatable in a clockwise direction to start the table motor and table, and rotatable in an opposite direction to stop the table motor and disconnect the power drive. The table knob may also be pressed downwardly by the operator to cause the table motor to be 10 stopped and the table drive to be disconnected when the table reaches the end of its travel in the direction in which it is moving at the time of pressing the knob. The table knob 759 is rigidly secured, as best shown in Fig. 33, to the upper 15 end of a rotatable and axially movable switch control rod 760 which is held normally in a raised rest position by means of a compression 20 spring not specifically illustrated, since the construction and mode of operation of the rod 760 25 and switches controlled thereby is identical with that of the headstock control rod 741 except for certain differences to be pointed out. There are rigidly secured to the control rod 760 a table 30 starting switch actuating arm 764 (see Figs. 33 30 and 38) and a stop switch control arm 766. The table starting switch comprises a plunger 768 which carries two switch arms 770 and 772 and is normally held in a rest position to the left in engagement with the lever arm 764, as shown in 35 Fig. 33, by means of a compression spring 774, in which position the switch arm 770 engages the contacts 50—51. The table stop switch similarly comprises a switch plunger 778 having mounted thereon switch arms 780 and 782 and is 40 provided at one end with an enlarged head which engages with a forked portion of the switch lever arm 766. A compression spring 784 tends normally to move the plunger to the right, as shown in Fig. 33, so that the switch arm 782 is normally 45 positioned to close the contacts 44—53. The table end stop switch comprises a switch plunger 786 which carries switch arms 788 and 790 and is arranged to engage against one arm of a small bell-crank lever 792, the other arm of which 50 engages the lower end of the table switch control rod 760. A compression spring 794 tends normally to maintain the switch plunger 786 to the left, as illustrated in Fig. 33, with the switch arm 790 out of engagement with the contacts 51—52. 55

The operation of the table motor is controlled from the table knob 759 and the starting and stopping switches above described by means of a number of secondary switch connections which include table dwell relays TR1 and TR2, generator field reversing contactors L and R, a hand wheel solenoid contactor HWS; under voltage contactor UV, table line and dynamic brake contactor LE1; counter electromotive forces relay CEMF; table slow speed contactor SS and a 60 table slow-down contactor S. The table dwell relays TR1 and TR2 are carried on a panel 796 illustrated at the top of the wiring diagram Figure 47, the table slow-down contactor S is mounted on the panel 758 and the remaining of the 65 above mentioned switches are located on a panel 798, as best shown in Fig. 47.

For starting the table if it be assumed that the several controls of the machine hereinafter more 70 fully to be described are set for grind position, 75

5 knob control, long dwell, and run position, the turning of the table knob 759 in a clockwise direction causes the lever arm 764 to engage with and move the switch plunger 768 to the right to close the switch contacts 53—55 and simultaneously to open the contacts 50—51, thus energizing coil UV. Contact UV 67—68 closes, energizing LE1 and either L or R coil, depending upon the position of the reversing lever. It will be hereinafter assumed that coil R is energized. Contact UV 22—23 closes, decreasing the table dynamic braking resistance, and contact UV 38—39 closes, energizing coil HWS which, in turn, energizes the solenoid 200 to disconnect the hand wheel from the table and engage the table drive to the table motor 132. Contact LE1 17—19 closes, starting the table motor and energizing coil CEMF, and contact LE1 20—21 opens, disconnecting the dynamic braking resistor R⁴. Counter EMF 3—38 closes, contact R 65—66 opens, thus preventing coil L from becoming energized, contact R 68—4 closes a holding circuit to the LE1 and R coils, contact R 56—57 closes, energizing coil S, thus eliminating the table slow down hereinafter to be described, and contacts R 14—15 and R 16—4 close, energizing the table generator field so that the table will traverse to the right. Contact R 3—60 closes, energizing coil TR 2. Contact TR 2 69—70 opens, and contact TR 23—59 closes, energizing coil TR1. Contact TR1 70—4 opens. The contacts TR2 69—70 and TR1 70—4 must both close before a table reversal can take place. Contact HWS 71—72 opens, disconnecting the hand wheel fast-slow selector switch, and contact HWS 73—72 closes, placing the power fast-slow selector switch in series with coil SS. Contact S 12—13 closes, giving the table motor a speed, as determined by the table field rheostat 797. The setting of the rheostat 797 is controlled manually by means of a knob 799 on the panel 733 as best shown in Figs. 1 and 40.

If it is now desired to stop the table traverse to the right, the operator may turn the table control knob 759 to the left or in a counter-clockwise direction to stop position, thus causing the switch lever arm 766 to move the switch plunger 778 to the left to disengage the switch contact 44—53, causing coils UV and S to be de-energized. Contact UV 54—55 opens to maintain coil UV in a de-energizing state, contact UV 67—68 opens de-energizing coils LE1 and R, contact UV 29—38 opens, and contact UV 22—23 opens, making the entire dynamic braking resistance available. Contact S 12—13 opens placing the total resistance of the rheostat in series with the table generator field. Contact LE1 17—19 opens, disconnecting the table motor, and contact LE1 20—21 closes connecting the dynamic braking resistance so as to bring the table motor to a rapid stop. Contact R 65—66 closes, contact R 68—4 opens, contact R 3—60 opens de-energizing coil TR2, contact R 56—57 opens, and contacts R 14—15 and R 4—16 open, de-energizing the table generator field. Contact TR2 69—70 closes, and contact TR2 3—59 opens, de-energizing coil TR1 and thus causing contact TR1 70—4 to close. The coil CEMF does not de-energize until the table motor has slowed down considerably. This holds the table drive clutch engaged with the motor during the stopping period. Contact CEMF 3—38 opens, de-energizing coil HWS. Contact HWS 88—94 opens, de-energizing the hand wheel solenoid which engages the hand wheel.

75 Assuming that the table is travelling to the

right and that the reversing lever is shifted by engagement with the table dog 260 to reverse the direction of travel of the table, the movement of the reversing lever to the right, as best shown in Figs. 40, and 43 to 46 inclusive, first operates to open the right slow-down contact 55—56, as the switch plunger 304 moves to its low position following the movement of the cam lever 292 which passes from the intermediate to the low portion of the reversing switch cam 290. The opening of the switch contact 55—56 de-energizes the coil S so that contact S 12—13 opens to throw in the entire resistance of the rheostat 797 to drive the table at a predetermined low speed, slowing down the table motor. Subsequently, as the reversing lever nears the limit of its movement to the right, the right limit contact 3—63 opens as the switch plunger 306 of the reversing switch is moved to its highest position by the movement of the cam lever 294 onto the highest portion of the switch reversing cam 290, so that the coil R is de-energized. Contact R 65—66 now closes, contact R 56—57 opens, contacts R 14—15 and R 4—16 open de-energizing the table generator field, and contact R 3—60 opens de-energizing coil TR2. Coil LE1 is de-energized by the opening of contact R 68—4. Contact LE1 17—19 opens, stopping the table motor and contact LE1 20—21 closes forming a dynamic braking circuit which brings the table motor to a rapid stop. The CEMF coil is de-energized as the motor finally stops and contact CEMF 3—38 opens, deenergizing HWS coil which, in turn releases the hand wheel solenoid. Assuming a long dwell position of the dwell adjusting switch designated at 841 in Figs. 1, 40 and 48, the continued operation of the subsidiary electrical connections will be as follows:—After a predetermined length of time which may, for example, amount to three-quarters of a second after coil TR2 is de-energized, it operates to close contact TR2 69—70 and to open contact TR2 3—59, de-energizing coil TR1 which, after the further delay preferably adjusted to three-quarters of a second, operates similarly to close contact TR1 70—4. The closing of contact TR1 70—4 energizes coil LE1 and L. Contact LE1 17—19 closes, starting the table motor, and contact LE1 20—21 opens, disconnecting the dynamic braking resistance. Contact L 63—64 opens, making it impossible to energize coil R, contact L 68—4 closes holding circuit for coils LE1 and L, contact L 55—56 closes energizing coil S, thus eliminating the slow-down, contacts L 4—16 and L 14—16 close, energizing the table generator field in an opposite direction from that in which it was connected during the traverse to the right and contact L 3—60 closes energizing coil TR2. Contact S 12—13 closes, giving the table motor speed as controlled by the rheostat in the table generator field. Contact TR2 69—70 opens, and contact TR2 3—59 closes energizing coil TR1 causing contact TR1 70—4 to open.

Assuming that the table is travelling to the right and that it is desired to operate the end stop control to cause the table to stop when it reaches the limit of its travel to the right, the operator presses downwardly upon the table knob 759, closing the end stop switch contact 51—52. Assuming that the controls of the machine are set for grind position, knob control, long dwell and run position, the operation of the subsidiary switch connections to stop the table travelling to the right, will be as follows: The closing of the contact 51—52 energizes an end stop contactor coil 75

ES supported on the panel 798 which is arranged to form a holding circuit for itself and to stop the table at the end of its stroke by holding the circuit open to the reverse contactors L and R 5 after the limit switch has been operated, and permits the power-manual clutch to be shifted to hand wheel position. When coil ES is energized, the contact ES 51—52 closes, forming the holding circuit, contact ES 68—69 opens, and contact ES 10 3—39 opens. When the reversing lever is now moved to its reversing position by engagement with the table dog 260, coils LE1, R, TR1, TR2, CEMF, and S are de-energized as previously described in connection with the reversal of the 15 table drive. Contact CEMF 3—38 opens, de-energizing coil HWS, which causes the power-manual clutch to shift to hand wheel position. Contact TR2 69—70 closes, and contact TR2 3—39 opens after its dwell, de-energizing TR1. Contact 20 TR1 70—4 closes after its dwell. The coils LE1 and L are not energized because of the open contact ES 68—69, leaving the table in its stop position at the extreme right.

In accordance with the present invention, a 25 novel and improved manually operable control is provided for the cross feed rapid movement which is well arranged for convenient and safe manipulation by the operator, and to this end has embodied therein certain control devices particularly designed to prevent the wheel spindle slide and grinding wheel from being inadvertently advanced at the rapid rate into an interfering position with relation to the work piece or other machine parts. For the manual control of the 30 cross feed rapid movement, a control knob 800 is mounted on the control panel 733 and is arranged to be rotated in a clockwise direction to render the cross feed rapid movement operative to retract the wheel spindle carriage 112, and is 35 arranged to be moved in a counter-clockwise direction to cause the wheel spindle carriage to be rapidly moved to its advanced position. The knob 800 is rigidly secured to the upper end of a short rock shaft 802 which has secured thereto 40 a lever arm 804 connected through a link 806 to an arm 808 secured to the upper end of a switch control rod 810. There are rigidly secured to the control rod 810 an advancing switch actuating lever arm 812 and a retracting switch actuating lever arm 814. The rapid movement advancing 45 switch comprises a switch plunger 816 which carries two switch arms 818 and 820 and is normally held to the right with an enlarged head formed on the end thereof in engagement with a 50 forked portion of the lever arm 812 and with the switch arm 818 out of engagement with the contact 28—29 by means of a compression spring 822. The rapid movement retracting switch 55 comprises a switch plunger 824 which carries two switch arms 826 and 828 and is normally held to the left in engagement with the switch lever arm 814 and with the switch arm 828 out of engagement with the contact 27—28 by means of a compression spring 830.

60 The cross feed rapid movement control knob 800 and switch connections above described operate to advance or to retract the wheel spindle carriage through subsidiary switch connections which comprise a wheel slide forward contactor F and a wheel slide back contactor B supported on a switch panel 831 (see Fig. 47). Assuming that the wheel slide is in its retracted position and that the machine is set for grind position and knob control, the operator to advance the 65 wheel spindle carriage turns the control knob 800

in a counterclockwise direction causing the switch plunger 816 to be moved to the left to close the contact 28—29 energizing coil F. Contacts F 89—90, F 86—T22, and F 88—91 close starting the wheel slide motor which runs the wheel slide 5 forward. Contact F 24—25 forms a holding circuit. At the end of a one-half revolution of the crank shaft 522 and as the wheel spindle carriage reaches the limit of its advancing movement, the follower 612 rides off of the high portion of the cam 608, 610, causing the limit switch contact 30—32 to open and the contact 31—32 to close, thus de-energizing the coil F to stop the motor and set the brake 580. With the construction and arrangement of the electrical connections above described, it will readily be seen that if the wheel spindle carriage were already in an advanced position when the knob 800 was turned in a counterclockwise direction, nothing could happen since the limit switch contact 30—32 20 would then be open, thus preventing the energizing of the coil F.

In accordance with one feature of the present invention, a control device is provided to prevent the accidental advance of the wheel spindle carriage at a rapid rate from a position which is likely to bring the grinding wheel directly into interfering engagement with the work piece. As previously pointed out, when the machine is to be operated by knob control, it is the usual practice first to operate the cross feed rapid movement to bring the grinding wheel in close proximity to the work and thereafter to start the cross feed. At the end of the operation the operator first backs off the cross feed hand wheel to its 35 full extent and thereafter operates the cross feed rapid movement to move the grinding wheel well clear of the work piece. It will readily be seen that if the order of the operation upon a fresh work piece were accidentally to be reversed, the 40 cross feed hand wheel being turned either partially or wholly to depth and the cross feed rapid movement being thereafter employed to advance the grinding wheel, the grinding wheel would necessarily move into interfering engagement 45 with the work. In accordance with the present invention, the electrical connections for controlling the operation of the cross feed rapid movement from the table knob 800 are constructed and arranged to prevent the rapid movement 50 advance of the wheel spindle carriage except when the cross feed hand wheel is in its fully retracted position. To this end a contact designated as RC 29—25 is provided in the circuit for energizing the F coil which is adapted to be closed 55 only upon the energizing of the auxiliary relay RC, which in turn is controlled by the automatic hand wheel control switch contact 3—35. As above described, the automatic hand wheel control switch contact 3—35 is normally maintained 60 in an open position and is closed only by the downward movement of the control slide 480 as the cross feed hand wheel is moved to its fully retracted position.

Assuming that the wheel slide is in its advance 65 position and that the machine controls are set, as above described, the operator to retract the wheel spindle carriage turns the control knob 800 in a clockwise direction causing the switch plunger 824 to be moved to the right to close the 70 contacts 28—27 energizing the coil B. Contacts B 89—90, B 86—T22, and B 88—91 are closed to start the wheel slide motor and run the table back. Contact B 24—27 forms a holding circuit. At the end of a one-half revolution of the crank 75

shaft 522, and as the wheel spindle carriage reaches the limit of its retracting movement, the follower 612 rides on the high portion of the cam 68, 610, opening limit switch contact 31—32 and closing the limit switch contact 30—32 de-energizing the coil B to stop the motor and set the brake 580.

In accordance with another feature of the present invention, a manually operable control switch member 834 is provided on the panel 733 which may be set alternatively to cause each of the headstock and table knobs to operate separately, as above described, to control the operation respectively of the headstock and table, or may be set to render the subsidiary switch connections for controlling the table subject to the headstock control knob 740 so that the operation of the headstock knob to start the headstock will simultaneously start the table. To this end the control switch 834 is arranged alternatively to close switch contact 44—50 for the start headstock alone position or to close contact 55—49 for the start headstock and table position. It may be noted also that the actuation of the headstock control knob to stop the headstock acts also to stop the table irrespective of the setting of the selector switch member 834.

In accordance with another feature of the present invention, there is provided on the control panel 733 a hand wheel fast-slow selector switch member 838 which is arranged to control the position of the fast-slow clutch 180 to determine the rate of travel of the table during manual operation of the table hand wheel. This switch, as best shown in the electrical diagram 48 and the explanatory electrical diagram Fig. 49, is arranged for the fast position of the switch member 838 to break the contact 3—71 to de-energize the table slow speed contactor SS, thus causing the SS contact 88—95 to open de-energizing the slow-fast clutch solenoid 226, so that the clutch is permitted to move to high speed position. The alternative slow position of the switch 838 operates to close the switch contact 3—71 energizing the slow speed contactor SS to close the SS contact 88—95 and energize the solenoid 226 to shift the clutch to slow speed position.

Also provided on the panel 733 is a table power fast-slow control switch 840 which is arranged to control the position of the fast-slow clutch 180 during the power operation of the table and has alternative operating positions corresponding to the fast and slow position of the clutch 180. The control switch 840 is arranged in fast position to open the switch contact 3—73 to de-energize the slow speed contactor SS which operates, as above described, to shift the fast-slow clutch 180 to fast position. The movement of the switch member 840 to slow position operates to close contact 3—73 to energize the slow speed contactor SS which, in turn, causes the clutch to be moved to its slow position.

Further in accordance with the present invention, switch connections are provided for selectively rendering the hand wheel or power fast-slow switch members 838 or 840 operative to control the position of the fast-slow clutch in accordance with whether the power-manual clutch is set for power or hand wheel operation of the table. To this end switch connections are provided in each of the hand wheel and power fast-slow selector switch circuits which are controlled from the hand wheel solenoid contactor HWS above described which operates when energized to energize the power manual clutch solenoid

shift the clutch to power position. HWS contact 13—72 is provided in series with the power fast-slow selector switch and HWS contact 71—72 is provided in series with the hand wheel fast-slow selector switch, these contacts being arranged so that the energizing of the HWS coil for power operation of the table operates to open HWS contact 71—72 and simultaneously to close HWS contact 13—72 to render the fast-slow clutch 180 subject to the power selector switch 840, and the de-energizing of the HWS coil to return the manual-power clutch 150 to hand wheel position similarly operates to open HWS contact 73—72 and to close HWS contact 71—72 to render the fast-slow clutch 180 subject to the hand wheel fast-slow selector switch.

In accordance with another feature of the present invention, there is provided on the panel 733, a plunge cut selector switch 842 having alternative run and stop positions which is arranged when moved to stop or plunge cut position to prevent the movement of the table power manual clutch 150 to power position, and thus to prevent the power operation of the table. This switch is provided particularly to set the machine for plunge cuts so that during a plunge cut operation the table cannot be inadvertently started by the manipulation of any of the controls above described which might otherwise operate to start table movement. The selector switch 842 is arranged to control contacts 38—37 and 55—57. For the run position of the switch 842, contact 38—37 is closed to provide circuit to the solenoid contact or HWS and contact 55—57 is open. When the switch is shifted to stop or plunge-cut position, switch contact 38—37 opens disconnecting HWS coil so that the power manual clutch solenoid 200 cannot be energized to shift the clutch to power position. At the same time the contact 55—57 closes to maintain the table slow-down contactor energized, thus eliminating the slow-down of the table motor. This has been found desirable so that the table motor which may be utilized at this time to drive the power cross feed will not be accidentally slowed down by an inadvertent moving of the table reversing lever.

In order to set up the machine for power operation of the cross feed when the selector switch 842 is set in stop position for plunge cut grinding, the clutch 402 is shifted to connect the crank 394 and cross feed pawl 376 for continuous operation from the table motor 132 which may be started and stopped to start and stop power operation of the cross feed pawl either by the actuation of the table control knob 759, or by operation of the headstock control knob 740, if the selector switch 834 is set in start headstock and table position.

In accordance with another feature of the present invention, electrically controlled devices are provided which may be operated from the cross feed hand wheel to automatically control the start and stop of the head stock, the supply of coolant, the power cross feed and, if so desired, the table reciprocation. This control is provided particularly to enable the operator to rapidly substitute a new work piece in the machine and again place the machine in operation when a large number of identical pieces are to be operated upon. The electrically controlled devices above referred to, may be rendered operative or inoperative to provide a unified control of the several cooperating units from the cross feed hand wheel by means of a selector switch

member 850 which is arranged for alternative knob control and automatic hand wheel control positions. The movement of the switch member 850 from knob to automatic hand wheel position, operates to close a contact 3-33 to energize an auxiliary relay AR, thus bringing the headstock, coolant flow, table reciprocation, and power cross feed under the control of the hand wheel automatic switch contact 3-35 which, as above pointed out, is controlled by the movement of the cross feed hand wheel 344.

The operation of the electrical connections to provide an automatic control of the machine from the cross feed hand wheel 344, may be briefly described as follows: When the selector switch 850 is turned to the hand wheel control position, the closing of contact 3-33 operates to energize coil AR. Contact AR 24-28 opens disconnecting the cross feed rapid movement control knob 800. Contact AR 24-26 closes to make the RC coil contacts effective to control the wheel slide rapid movement. Contact AR 44-46 opens holding circuit for coil CR and contact AR 44-48 closes making RC relay effective for controlling the CR coil for starting the headstock motor. Under these conditions, when the hand wheel is now revolved in a clockwise direction to its fully backed-off position, the pin 506 engages with and depresses the control slide 480 to close the switch contact 3-35 so that the auxiliary relay coil RC is energized. Contact RC 29-25 closes, contact RC 25-26 opens to prevent coil F from becoming energized, and contact RC 26-27 closes energizing coil B and causing the wheel spindle carriage to be moved rapidly backwards. Contact RC 47-48 opens keeping coil CR de-energized. It will be seen that the closing of the automatic hand wheel switch contacts 3-35 has caused the headstock motor to be stopped, the coolant supply to be turned off, and the cross feed rapid movement to be rendered operative to rapidly retract the grinding wheel carriage.

The above cycle of operations in stopping the machine has presupposed that the headstock and table selector switch member 834 has been set for headstock alone position, so that contacts 44-50 are closed and contact 49-55 is opened. The table motor is not operated since contacts 49-55 are open to prevent the engaging of the table control relay UV. Under these conditions, the power cross feed is inoperative, and it is assumed that the work is fed to depth by hand operation of the cross feed hand wheel.

If it is desired to start and stop the table motor either for a continuous power cross feed or to start and stop the table reciprocation, the selector switch 834 must be set for start headstock and table position to open the contact 44-50 and close the contact 49-55 so that the closing of AR contact 49-47 will operate to bring the relay UV and table motor controlled thereby under the control of automatic hand wheel relay RC.

A further setting of the controls is necessary to determine whether table reciprocation shall be brought under the control of the automatic cross feed hand wheel control. This setting of the controls is determined by the position of the table plunge cut selector switch 842, which operates in stop or plunge cut position to prevent the energizing of relay HWS and subsequent shifting of the power manual clutch to power position.

After the finished work piece has been removed and a new piece placed in position in the machine, the operator, in order to start the machine again 76 in operation, advances the cross feed hand wheel

slightly so that the pin 506 is moved out of engagement with the cam surface 510 to permit the control slide 480 to move upwardly and open the automatic switch contact 3-35. The opening of the contact 3-35 energizes the coil RC. RC contacts 29-25 and 26-27 open. Contact RC 25-26 closes energizing coil F to move the wheel slide forward. Contact RC 48-47 closes energizing coil CR to start the headstock motor and to turn on the coolant supply. The continued operation depends on the position of the several controls, as above pointed out. If it be assumed that the selector switch 834 is in headstock alone position, the table motor is prevented from starting by the opening selector switch contact 55-49. The operator will, therefore, continue to advance the cross feed hand wheel manually to depth. If it be assumed that the selector switch 834 is in the starting headstock and table position, the closing of RC contact 48-47 operates to energize coil UV to start the table motor, the power actuation of the cross feed pawl 376, and the reciprocation of the table, depending of course upon the position of the table plunge cut selector switch 842. At this time the operator, in order to render the power cross feed effective, moves the pawl control lever 463 downwardly to permit the engagement of the pawl with the ratchet teeth.

In accordance with the present invention, an electrically operated truing control is provided 30 which is arranged to shift the control of the several operating units of the machine from the manually operable controls above described so that these units may be permitted to operate only in a manner consistent with the operation of truing the grinding wheel. The truing control comprises a truing knob 854 which is mounted on the control panel 733 and is arranged to be turned to the right to true position or alternatively to the left to an inoperative or grind position. Associated with the truing knob 854 is a switch comprising a contact 3-34 which is arranged when closed to energize a truing speed contactor switch TS, and a contact 57-58 which is arranged when opened to de-energize the slow-down contactor S. 45 With the switch in grind or inoperative position, contact 3-34 is opened and contact 57-58 is closed.

The movement of the truing control knob 854 to truing position to energize the truing speed 50 contactor TS, operates to perform a number of functions in order to insure that the several operating units of the machine will operate only in the desired manner. The table speed is adjusted automatically for the slowest rate of power operation regardless of the setting of the various controls. The coolant is connected to be turned on upon starting of the table reciprocation irrespective of whether the headstock motor is running or not. The knob 800 is rendered inoperative 60 to cause the wheel spindle carriage to be either advanced or retracted to prevent possible injury to the machine through accidental or inadvertent handling of this knob. The table dwell mechanism is disconnected to eliminate any delay in 65 table reversal. The plunge cut selector switch 842 is disconnected so that it becomes unnecessary for the operator to shift the setting of this switch for truing as, for instance, where it is found necessary to interrupt a series of plunge grinding operations to true the grinding wheel. The wheel spindle reciprocating mechanism is rendered inoperative to prevent reciprocation of the grinding wheel during the truing operation. The electrical connections controlled by the automatic hand 70

wheel control selector switch 850 are disabled so that it becomes unnecessary for the operator to shift the position of this switch before adjusting the position of the grinding wheel with relation to the truing tool.

The operation of the electrical connections to shift the control of the several operating units for truing the grinding wheel is as follows:—The operator turns the grind truing selector switch 854 to true position so that contact 3—34 is closed to energize the truing speed contactor TS and contact 57—58 is opened to de-energize the table slow-down contactor S. Contact TS 88—97 opens, breaking the circuit to the oscillator solenoid 105, thus making it impossible to oscillate the grinding wheel. Contact TS 32—4 opens, breaking the circuit to the F and B coils, to render the cross feed rapid movement control knob 800 inoperative to either advance or retract the wheel spindle carriage. The opening of the contact TS 32—4 also breaks the circuit through the control relay coil AR, thus rendering the knob-automatic hand wheel selector switch 850 inoperative so that the cross feed hand wheel 344 may be rotated to advance or retract the grinding wheel alone irrespective of the setting of the selector switch 850. Contact TS 38—37 closes so that the power-manual clutch will be subject to the control of the table starting button irrespective of the position of the plunge cut selector switch 842. Contact TS 38—40 closes so that the pressing of the table start button will operate to energize the coolant control relay CS to turn on the supply of coolant. The contact TS 60—61 opens de-energizing coils table dwell relays TR1 and TR2 to eliminate table dwell upon reversal. Contact TS 3—73 closes, so that the pressing of the table start button by energizing the coil HWS will operate to energize the table slow speed contactor SS to shift the fast-slow clutch 180 to slow position irrespective of the setting of the power fast-slow selector switch 840.

The operator has now only to adjust the truing attachment in position on the machine table to adjust the position of the grinding wheel with relation to the truing tool by manipulation of the cross feed hand wheel, and then to move the table reversing lever 266 forwardly about its pivot 278 out of the path of the table dogs in order to set up the machine for the performance of the truing operation. The operator now turns the table control knob 158 to start position closing contact 53—55 to energize the under voltage contactor UV. UV contact 39—38 closes energizing coil HWS and coil CS through the closed TS contact 38—40. At substantially the same instant, contact HWS 13—72 closes energizing coil SS to shift the slow-fast clutch 180 to slow position. Contact HWS 88—94 closes energizing the hand wheel solenoid 200 thus shifting the power-manual clutch 150 to power position to start the table. Contacts CS 88—92 and CS 92—93 close energizing coolant solenoid which starts the coolant flowing. Contact SS 88—95 closes energizing the slow speed solenoid which operates the slow-fast clutch 180 to shift the table drive gear ratio to the slow speed series. At the end of the truing operation the operator turns the table control knob 158 to stop position to open contact 44—53 to de-energize under voltage relay UV, causing the contacts previously closed by the energizing of this coil to open de-energizing the coils LE1, HWS, CS and SS to stop the table motor, shift the power manual clutch to hand wheel position and shut off the supply of coolant. The

turning of the truing control knob to grind position now operates to open contact 3—34 and close contact 57—58 thus de-energizing the truing speed contactor TS and re-establishing the circuit to the slow-down contactor S to shift the control of the several operating units of the machine back to the several manual controls on the machine.

The invention having been described, what is claimed is:—

1. A grinding machine having, in combination stock, a variable speed electric motor for driving with a grinding wheel spindle, a rotary headstock, manually operable means adjustable to secure a plurality of predetermined motor speeds, a manually operable starting and stopping control for the motor, switch connections controlled thereby for driving the motor at a speed determined by said adjustment, a manually operable headstock jog control, and switch connections controlled thereby to drive the motor at a minimum rate independently of said adjustment, and a single manually operable controller member movable selectively to actuate said starting and stopping control and said headstock jog control.

2. A grinding machine including a bed, a table member movable on the bed, a rotary work driving member carried by the table, a motor for driving the work driving member, a rotatable and axially movable control member, and switch connections rendered operative by the rotation of said control member in one direction to start the motor, by the rotation of said control member in an opposite direction to stop the motor, and by an axial movement of the control member to jog the motor.

3. A grinding machine having in combination with a grinding wheel spindle, a rotary headstock, an electric motor for driving the headstock, a starting switch and connections for the motor acting when rendered operative to connect the motor for continuous operation, a motor stop switch, a motor jog switch, a manually rotatable and axially movable starting and stopping control knob, connections rendered operative by the rotation of said knob in one direction to actuate said starting switch, and rendered operative by the rotation of the knob in the opposite direction to actuate said stop switch, and by axial movement thereof to actuate said jog switch.

4. A grinding machine having in combination with a grinding wheel spindle, a rotary headstock, a variable speed electric motor for driving the headstock, means adjustable to secure a plurality of predetermined motor speeds, and control devices including a motor starting switch acting when rendered operative to connect the motor for continuous operation at a speed determined by the adjustment of said means, a motor stop switch, a motor jog switch connected to drive the motor at a minimum rate independent of said adjustment, a manually rotatable and axially movable control knob, connections rendered operative by the rotation of said knob in one direction to actuate said starting switch, and rendered operative by the rotation of the knob in the opposite direction to actuate said stop switch, and by axial movement of the knob to actuate said jog switch, and spring means tending normally to move said control knob axially to disengage said jog switch.

5. A grinding machine having, in combination, a grinding wheel spindle, means for continuously driving the spindle, a rotary headstock, power

means for rotating the headstock, a manually operable starting and stopping control for the headstock, means for supplying coolant to the point of grinding contact, means actuated by 5 said starting and stopping control for the headstock simultaneously to turn on and shut off the supply of coolant, a jog control element, connections actuated thereby for independently starting and stopping the headstock, and connections 10 actuated by said jog control element during the operation of the headstock to shut off and turn on the supply of coolant.

6. A grinding machine including a bed, a table member movable on the bed, a rotary work 15 driving member carried on the bed, a motor for driving the work driving member, a control member movable in a plurality of planes, and switch connections rendered operative by movement of 20 said control member in one plane to start and stop the motor, and by movement of said control member in another plane to jog the motor.

7. A grinding machine having in combination with a grinding wheel spindle, a reciprocable work table, a rotary headstock carried thereon, power means for driving the table, means for reversing the table drive at the end of the table 25 travel in each direction, power means for driving the headstock, manually operable switch connections to start and stop the headstock, electrical- 30 ly operated means for starting and stopping the table, electrical connections between said switch connections and said electrically operated means whereby the operation of said manually operable switch connections acts simultaneously to control the operation of said electrically operated 35 means, and a selector control element operable to render said electrical connections alternatively operative or inoperative.

8. A grinding machine including a bed, a reciprocable table member movable on the bed, a rotary work driving member carried on the table member, electrical connections whereby the rotary work driving member may be connected for power operation, electrical connections whereby 40 the table may be connected for power operation, a control member for said former electrical connections to start and stop the rotary work driving member, a control member for said latter electrical connections for starting and stopping 45 the table, and a selector control member whereby said control member for the rotary work driving member may be rendered operative to start and stop said rotary member and simultaneously to start and stop the table.

55 9. A grinding machine having in combination with a grinding wheel spindle, a reciprocable work table, a rotary headstock carried thereon, power means for driving the table, power means for driving the headstock, a manually operable control device, and connections controlled thereby for starting and stopping the headstock, a second manually operable control device, connections controlled thereby for starting and stopping the table, a manually operable selector control device, and connections controlled thereby for connecting one of said first two control devices to simultaneously start and stop said headstock and table.

10. A grinding machine having in combination, 70 a grinding wheel spindle, power means for continuously driving the spindle, a reciprocable work table, a rotary headstock carried thereby, an electric motor and connections including a clutch for driving the table, an electric motor for driving the headstock, a manually operable con-

trol including switch connections for starting and stopping the headstock motor, a manually operable control including switch connections for starting and stopping the table motor and simultaneously for engaging and disengaging 5 said clutch, and a manually operable selector device including a switch whereby said headstock control is rendered operative through said switch connections to control also the operation of said table motor and clutch. 10

11. In a grinding machine, the combination of a reciprocable work table, a rotary work holder carried thereon, a rotary grinding wheel spindle, a wheel carriage movable toward and away from the work, power means for rotating the work 15 holder, a reversible electric motor and connections including a power-manual clutch for reciprocating the table, a table hand wheel, means controlled from the table for reversing the motor to reverse the direction of table travel, a cross 20 feed for feeding the carriage and spindle carried thereby toward the work, connections from the table motor for actuating the cross feed, a manually operable table power control arranged to start the motor and simultaneously to shift the 25 clutch from manual to power position, and a plunge cut control device including connections operable to maintain said clutch in manual position independently of movement of said table power control to start and stop the table motor. 30

12. In a grinding machine, the combination of a reciprocable work table, a rotary work holder carried thereon, a rotary grinding wheel spindle, a wheel carriage movable toward and away from the work, power means including a table motor 35 and a power-manual clutch for reciprocating the table, a table hand wheel, a cross feed for feeding the carriage and spindle carried thereby toward the work, connections from the table motor connectible to actuate said cross feed, a table power control including means to start or stop the table motor and simultaneously for shifting said clutch from manual to power position or vice versa, and a plunge cut control device including connections operable to maintain 45 said clutch in manual position independently of the operation of said table power control to start and stop the table motor.

13. In a grinding machine, the combination of a reciprocable work table, a rotary work holder 50 carried thereon, a rotary grinding wheel spindle, a wheel spindle carriage movable toward and away from the work, operating means for the table and wheel carriage constructed and arranged for the performance of alternative reciprocating 55 or plunge cut grinding operations, said means comprising power means for reciprocating the table, a manually operable power control including a clutch shiftable to start and stop table power operation and manually operable means to shift the clutch, a cross feed for feeding the carriage and spindle carried thereby toward the work, and a plunge cut control device including a separate manually operable control element and connections therefrom operable to disable said manually operable means to control the clutch, and to position said clutch in table stop position. 65

14. In a grinding machine, the combination of a reciprocable work table, a rotary work holder carried thereon, a rotary grinding wheel spindle, 70 a wheel carriage movable toward and away from the work, power means including a reversible electric motor for reciprocating the table, a starting and stopping switch for the motor, a cross feed for feeding the carriage and spindle carried there- 75

by toward the work, and a plunge cut control device including a manually operable table stop switch movable to render the motor inoperative to drive the table independently of said starting and stopping switch.

15. In a grinding machine, the combination of a reciprocable work table, a rotary work holder carried thereon, a rotary grinding wheel spindle, a wheel carriage movable toward and away from the work operating means for the table and wheel carriage constructed and arranged for the performance of alternative reciprocating or plunge cut grinding operations, said means comprising, power means for driving the table including a power transmitting connection shiftable to start and to stop the table from power operation, power means for rotating the headstock, a cross feed for feeding the carriage toward the work, a manually operable control for shifting said power transmitting connection to start and stop the table, a manually operable control to start and stop the headstock, a control element and connections controlled thereby whereby the headstock control is connected to effect the starting and stopping of the table simultaneously with the starting and stopping of the headstock, and a plunge cut control device including a manually operable table stop element, and connections therefrom operable to disconnect said manually operable control from the table power transmitting element and to shift said power transmitting element to table stop position.

16. In a grinding machine, the combination of a reciprocable work table, a rotary work holder carried thereon, a rotary grinding wheel spindle, a wheel carriage movable toward and away from the work, a cross feed for feeding the carriage and spindle carried thereby toward the work, a reversible electric motor and connections including a clutch for reciprocating the table, means controlled from the table for reversing the motor to reverse the direction of table travel, a manually operable table power control arranged to start the motor and simultaneously to engage the clutch, and a plunge cut control device including a manually operable control element movable to render said table manual control inoperative to engage the clutch.

17. In a grinding machine, the combination of a reciprocable work table, a rotary work holder carried thereon, a rotary grinding wheel spindle, a wheel carriage movable toward and away from the work, a reversible electric motor and connections including a clutch for reciprocating the table, a cross feed mechanism for the carriage and spindle carried thereby, connections from the table motor for actuating the cross feed, connections actuated by the reciprocatory movement of the table for actuating the cross feed, a control element movable for rendering one or the other of said connections operative to drive the cross feed, means controlled from the table for reversing the motor to reverse the direction of table travel, a manually operable table power control arranged to start the motor and simultaneously to engage the clutch, and a plunge cut control device including a manually operable control element movable to render said table manual control inoperative to engage the clutch.

18. In a grinding machine, the combination of a reciprocable work table, a rotary work holder carried thereon, a rotary grinding wheel spindle, a wheel carriage movable toward and away from the work, driving connections for the table including a table motor, manual table driving

means, a power-manual clutch shiftable to connect the table alternatively for power and manual operation, a cross feed mechanism for the carriage and spindle carried thereby, means for connecting the table motor to actuate the cross feed, means controlled from the table for reversing said motor to reverse the direction of table travel, a manually operable power table starting and stopping control and connections controlled thereby for starting the motor and simultaneously for shifting said clutch to power position, and a plunge cut control device including a manually operable control element movable to render said table power control inoperative to engage the clutch.

19. In a grinding machine, the combination of a reciprocable work table, a rotary work holder carried thereon, a rotary grinding wheel spindle, a wheel carriage movable toward and away from the work, a cross feed for feeding the carriage and spindle carried thereby toward the work, power means for rotating the work holder, a manually operable control for starting and stopping holder rotation, a reversible electric motor and connections including a clutch for reciprocating the table, means controlled from the table for reversing the motor to reverse the direction of table travel, a manually operable table power control arranged to start the motor and simultaneously to engage the clutch, a selector control element and connections whereby said manually operable control for starting and stopping holder rotation is connected simultaneously to effect the starting of the table motor and the engagement of the table clutch, and a plunge cut control device including a manually operable table stop element movable to prevent the engagement of said table clutch by either of said manually operable controls.

20. In a grinding machine, the combination of a bed, a grinding wheel carriage carried thereby and shiftable relatively thereto, a rotatable feed screw, means for rotating the screw to move the carriage at a feeding rate, and means for shifting the screw axially for rapid movement of the carriage comprising a crank, an oscillatory driving member driven thereby, and a power driving and stopping means for rotating said crank intermittently through successive 180° increments of rotation alternately to retract and thereafter to return the spindle carriage to operating position, and control means for stopping the crank in substantially dead center position with relation to the oscillatory driving member driven thereby.

21. In a grinding machine, the combination of a bed, a grinding wheel carriage carried thereby and shiftable relatively thereto, a rotatable feed screw, means for rotating the screw to move the carriage at a feeding rate, and means for shifting the screw axially for rapid movement of the carriage comprising a crank, an oscillatory driving member driven thereby, and power driving means for rotating the crank including means responsive to the shifting angular position of the crank to stop the crank at the completion of each successive half revolution thereof in substantially dead center position with relation to the oscillatory driving member driven thereby alternatively to retract and thereafter to return the spindle carriage to operating position.

22. In a grinding machine, the combination of a bed, a grinding wheel carriage carried thereby and movable relatively thereto, a rotatable feed screw, means for rotating the screw to shift the carriage at a feeding rate, and means for moving the screw axially for rapid movement of the car-

riage comprising an electric motor and connections therefrom for reciprocating said screw axially through a predetermined distance, a control switch for starting the motor, and connections including a timing device for stopping the motor to position the screw alternately at the limit of its movement in each direction.

23. In a grinding machine, the combination of a bed, a grinding wheel carriage carried thereby and shiftable relatively thereto, a rotatable feed screw, means for rotating the screw to shift the carriage at a feeding rate, and means for moving the screw axially for rapid movement of the carriage comprising a crank, a reciprocating driving member actuated thereby, a driving connection between the reciprocating member and feed screw to permit a yielding relative movement therebetween, positive stops for limiting the axial movement of the feed screw in each direction, power means for rotating the crank, means for stopping the rotation of the crank, and a control device therefor to stop the crank with the feed screw alternately at the limit of its movement in each direction.

24. In a grinding machine, the combination with a base, of a grinding wheel, a grinding wheel carriage movable on said base, a rotatable feed screw, means for rotating the screw to move the carriage at a feeding rate, and means for supporting and shifting said screw axially for rapid movement of the carriage including a sleeve on said screw supported against axial movement with relation thereto, positive stops for limiting axial movement of the sleeve and screw in each direction, a crank, a reciprocable shift lever actuated thereby, a connection between the sleeve and lever arranged to permit a limited relative movement therebetween, and arranged for the position of extreme throw of the lever in each direction to engage the sleeve and screw against the corresponding stop, spring take-up means between the lever and the sleeve, and power driving and stopping means for rotating said crank through successive half turns and for stopping the crank substantially in each of two alternate stop positions corresponding to the positions of extreme throw of said lever.

25. In a grinding machine, the combination of a bed, a grinding wheel carriage carried thereby and shiftable relatively thereto, a rotatable feed screw, means for rotating the screw to move the carriage at a feeding rate, and means for shifting the screw axially for rapid movement of the carriage comprising a rotatable driving member, an oscillatory member actuated thereby, a yielding connection in said means for shifting the screw inserted between said driving member and screw, positive stops for limiting axial movement of the feed screw in each direction against the pressure of said yielding connections, and power means acting when rendered operative to rotate said rotary driving member through successive increments of rotation alternately to retract and to return the spindle carriage to operating position.

26. In a grinding machine, the combination of a bed, a grinding wheel carriage carried thereby and shiftable relatively thereto, a rotatable feed screw, means for rotating the screw to move the carriage at a feeding rate, and means for shifting the screw axially for rapid movement of the carriage comprising a crank, a reciprocating shift member actuated thereby, a yielding driving connection between said reciprocating member and the feed screw, positive stops for limiting axial movement of the feed screw in each direction, an

electric motor connected to drive the crank, a starting switch for the motor, a stop switch for the motor, and connections from the crank for actuating said stop switch to stop the crank.

27. In a grinding machine, the combination of a bed, a grinding wheel carriage carried thereby and movable relatively thereto, a rotatable feed screw, means for rotating the screw to shift the carriage at a feeding rate, and means for moving the screw axially for rapid movement of the carriage comprising a rotatable driving member, an oscillatory member actuated thereby for alternately imparting advancing and retracting axial movements to said screw, an electric motor and braking unit, and connections therefrom for rotating said driving member, a starting switch connected to start the motor and release the brake, a stopping switch to disconnect the motor and set the brake, and connections controlled from said driving member for actuating said stopping switch to arrest said driving member.

28. In a grinding machine, the combination of a bed, a grinding wheel carriage carried thereby and movable relatively thereto, a rotatable feed screw means for rotating the screw to shift the carriage at a feeding rate, and means for moving the screw axially for rapid movement of the carriage comprising a crank, an oscillatory shift lever actuated thereby for alternately imparting advancing and retracting movements to the screw, yielding connections between said oscillatory shift lever and feed screw, positive stops for limiting axial movement of the feed screw in each direction against the pressure of said yielding connections, an electric motor and braking unit, and connections therefrom for rotating the crank, a control switch connected to start the motor and release the brake, and means acting automatically to stop the motor and set the brake upon each 180° increment of rotation of the crank to shift the feed screw from one of said limiting positions to the other.

29. In a grinding machine, the combination of a bed, a grinding wheel carriage carried thereby and shiftable relatively thereto, a rotatable feed screw, means for rotating the screw to shift the carriage at a feeding rate, and means for moving the screw axially for rapid movement of the carriage comprising a crank, a reciprocating driving member actuated thereby, a yielding driving connection between the reciprocating member and feed screw, positive stops for limiting the axial movement of the feed screw in each direction, an electric motor connected to drive the crank, and electrically operated connections for controlling the operation of the motor comprising starting switch connections, a cam on the crank having a rise and a drop surface thereon, and stop switch connections rendered operative thereby alternately to stop the motor with the feed screw in its advanced or retracted position, said cam comprising two disks having similar low and high portions relatively movable to permit an independent adjustment of the angular position of said rise and drop portions of the cam on the crank.

30. In a grinding machine, the combination of a bed, a grinding wheel carriage carried thereby and shiftable relatively thereto, a rotatable feed screw, means for rotating the screw to shift the carriage at a feeding rate, and means for moving the screw axially for rapid movement of the carriage comprising a crank, an oscillatory member actuated thereby for imparting alternate advancing and retracting axial movements to said screw,

- an electric motor and connections therefrom including reduction gearing for rotating said crank, starting switch connections for said motor, cam actuated stopping switch connections for said 5 motor, and a stopping switch control cam on said crank having two switch actuating surfaces separately adjustable on said crank to stop the motor with the feed screw alternately in its advanced and retracted positions.
- 10 31. In a grinding machine, the combination of a bed, a grinding wheel carriage carried thereby and shiftable relatively thereto, a rotatable feed screw, means for rotating the screw to move the carriage at a feeding rate, and means for 15 shifting the screw axially for rapid movement of the carriage comprising a crank, an oscillatory screw shift lever driven thereby, a power drive acting when rendered operative to rotate said crank intermittently through successive 180° increments of rotation alternatively to retract and thereafter to return the spindle carriage to operating position, a starting control for said power drive having alternative operating positions for advancing and retracting the carriage, and means 20 for synchronizing the starting control with said rotational movements of the crank to effect movement of the carriage only in the corresponding direction.
32. In a grinding machine, the combination of 25 a bed, a grinding wheel carriage carried thereby and shiftable relatively thereto, a rotatable feed screw, means for rotating the screw to move the carriage at a feeding rate, and means for shifting the screw axially for rapid movement of the carriage comprising a crank, an oscillatory screw shift lever driven thereby, an electric motor and connections therefrom for rotating the crank, and a starting and stopping circuit for the motor including a motor starting switch for advancing 30 the carriage, a motor starting switch for retracting the carriage, a motor stop switch having alternative positions to complete the starting circuit through one or the other of said starting switches, and means controlled by the rotational movement of the crank to shift said stopping switch from one to the other of said positions for each one-half revolution of the crank.
33. In a grinding machine, the combination of 35 a work support, a grinding wheel support, a grinding wheel cross feed for relatively moving said supports to advance and retract the grinding wheel with relation to the work comprising a rotatable shaft, a reciprocable feed pawl, a ratchet wheel supported normally to turn with the shaft and having thereon a stop surface to render said pawl inoperative to further rotate the ratchet, and means for adjusting the angular position of the ratchet with relation to the shaft to determine the depth of feed.
34. In a grinding machine, the combination of 40 a work support, a grinding wheel support, a grinding wheel cross feed for relatively moving said supports to advance and retract the grinding wheel with relation to the work comprising a rotatable shaft, a reciprocable feed pawl, a ratchet wheel supported normally to turn with the shaft and having thereon a stop surface to render said pawl inoperative to further rotate the ratchet, and a micrometer adjustment for turning back 45 the ratchet wheel relatively to said shaft from said stop position to permit a further advance of the ratchet wheel and shaft through an exactly determined distance.
35. In a grinding machine, the combination of 50 a work support, a grinding wheel support, a
- grinding wheel cross feed for relatively moving said supports to advance and retract the grinding wheel with relation to the work comprising a rotatable shaft, a reciprocable feed pawl, a ratchet wheel supported normally to turn with the shaft and having thereon a bare spot arranged to render said pawl inoperative to further rotate the ratchet, and a micrometer adjustment for turning back the ratchet wheel relatively to said shaft from the stop position determined by the engagement of the pawl with the last ratchet tooth 55 adjacent said spot to permit a further advance of the ratchet wheel and shaft connected thereto through an exactly determined angular distance.
36. In a grinding machine, the combination of 60 a work support, a grinding wheel, a grinding wheel support, a grinding wheel cross feed for relatively moving said supports to advance and retract the grinding wheel with relation to the work comprising a rotatable shaft, a reciprocable feed pawl, a ratchet wheel loosely supported to turn on said shaft and having thereon a stop surface arranged to render the pawl inoperative to further rotate the ratchet, a gear keyed to said shaft, a pinion rotatably mounted on the ratchet wheel to mesh with said gear, and a micrometer adjustment for locking said pinion in an adjustably determined angular position on said ratchet wheel.
37. In a grinding machine, the combination of 65 a work support, a grinding wheel, a grinding wheel support, a grinding wheel cross feed for relatively moving said supports to advance and retract the grinding wheel with relation to the work comprising a rotatable shaft, a reciprocable feed pawl, a ratchet wheel loosely supported to turn on said shaft and having thereon a stop surface arranged to render the pawl inoperative to further rotate the ratchet, a gear keyed to said shaft, a pinion rotatably mounted on the ratchet wheel to mesh with said gear and movable axially out of engagement to disconnect the ratchet wheel therefrom, and a micrometer adjustment including a dial splined to said pinion for locking the pinion in an adjustably determined angular 70 position on said ratchet.
38. In a grinding machine, the combination of 75 a work support, a grinding wheel spindle, a wheel spindle carriage movable toward and away from the work, a grinding wheel cross feed for moving the carriage to advance and retract the grinding wheel comprising a rotatable shaft, a cross feed hand wheel, means for connecting the hand wheel to rotate the shaft, a reciprocable feed pawl, a ratchet formed integrally with the hand wheel and having thereon a stop surface to render the pawl inoperative to further rotate the hand wheel, a stationary stop member, and a cooperating stop pin on the hand wheel arranged to positively limit the advance of the hand wheel upon the engagement of the pawl with said stop surface.
39. In a grinding machine, the combination of 80 a work support, a grinding wheel spindle, a wheel spindle carriage movable toward and away from the work, a grinding wheel cross feed for moving the carriage to advance and retract the grinding wheel comprising a rotatable shaft, a hand wheel supported normally to turn with the shaft, a reciprocable feed pawl, a ratchet formed integrally with the hand wheel and having thereon a stop surface to render said pawl inoperative to further rotate the hand wheel, a stationary stop member, a stop pin on the hand wheel arranged for engagement therewith to positively 85

- limit the advance of the hand wheel upon the engagement of the pawl with the stop surface, a micrometer adjustment for turning back the hand wheel relatively to the shaft from said stop position to permit a further advance of the ratchet wheel and shaft through an exactly predetermined distance, and means under the control of the operator for moving the stop member out of the path of the stop pin.
10. 40. In a grinding machine, the combination with a work holder, of a grinding wheel spindle, a spindle carriage movable toward and away from the work holder, a cross feed mechanism for the grinding wheel carriage including a cross feed hand wheel, a cross feed rapid movement for shifting the carriage at a rapid rate toward and away from the work, a manually operable control for said rapid movement, a control device for limiting the feeding and backing-off movements of the hand wheel, and a device controlled thereby to prevent the operation of said manually operable control to advance the carriage except with the hand wheel in its fully retracted position.
25. 41. In a grinding machine, the combination of a bed, a grinding wheel carriage carried thereby and shiftable relatively thereto, a rotatable feed screw, a manually operable cross feed member for rotating said screw to move the carriage at a feeding rate, power means for imparting an additional advancing or retracting movement to the carriage through a predetermined distance at a rapid rate, a manually operable control device for connecting said power means alternatively to 30 retract or advance the carriage, a device to prevent the operation of said power means to advance the carriage, and means rendered operative by the movement of the cross feed member in backing off the carriage to disconnect said device.
40. 42. In a grinding machine, the combination of a bed, a grinding wheel carriage carried thereby and shiftable relatively thereto, a rotatable feed screw, a manually operable cross feed member for rotating said screw to shift the carriage at a feeding rate, power means for imparting an additional advancing or retracting movement to the carriage through a predetermined distance at a rapid rate, a depth stop for limiting the feeding movement of the manually operable cross feed member at depth, a backing-off stop for limiting the reverse movement of the cross feed member to back off the carriage, a manually operable control device for connecting the power means alternatively to retract or advance the carriage, 50 a device to prevent the operation of said power means to advance the carriage, and means rendered operative by the movement of the cross feed member into engagement with said backing-off stop to disconnect said device.
60. 43. In a grinding machine, the combination of a bed, a grinding wheel carriage carried thereby and shiftable relatively thereto, a rotatable feed screw, a manually operable cross feed member for rotating said screw to shift the carriage at a feeding rate, an electric motor connected to impart an additional retracting or advancing movement to the carriage through a predetermined distance at a rapid rate, manually operable switch connections for connecting the motor alternatively to advance or retract the carriage, a switch connected to said switch connections normally operable to prevent the operation of said switch connections to advance the carriage, and a control element associated with said cross feed member rendered operative by the movement of
- the cross feed member in backing off the carriage to move said switch to inoperative position.
44. In a grinding machine, the combination of a work support, a grinding wheel spindle, a spindle carriage movable toward and away from the work, a cross feed mechanism for advancing and retracting the grinding wheel with relation to the work comprising a rotary feed member, a stop member secured thereto, a control slide supported adjacent the feed member having on one side thereof a feed stop abutment for engagement with said stop member, and on the other side thereof a backing-off stop abutment for engagement with said stop member to limit the backing-off movement of said feed member and simultaneously to move said slide.
45. In a grinding machine, the combination of a work support, a grinding wheel spindle, a wheel spindle carriage movable toward and away from the work, a grinding wheel cross feed for moving the carriage to advance and retract the grinding wheel comprising a cross feed hand wheel, a cross feed rapid movement for shifting the carriage at a rapid rate toward and away from the work, a manually operable control for said rapid movement, a control slide supported adjacent the hand wheel and having formed thereon a depth stop surface, a backing-off stop surface and a cammed slide actuating surface, a depth stop pin on the hand wheel arranged for engagement with said depth stop surface to limit the advancing movement of the hand wheel, a backing-off stop pin on the hand wheel arranged during the backing-off movement of the hand wheel for engagement with said cammed surface to move the slide and thereafter for engagement with said backing-off stop surface, a device acting normally to prevent operation of said manually operable control to advance the carriage, and connections rendered operative by the movement of the slide to render said device inoperative.
46. In a grinding machine, the combination with a work holder, of a grinding wheel spindle, a spindle carriage movable toward and away from the work holder, a cross feed mechanism for advancing and retracting the grinding wheel with relation to the work comprising a hand wheel, a control member movably supported on the machine adjacent the hand wheel, means actuated thereby for controlling machine operation, a feed stop pin on the hand wheel, a backing-off stop pin adjustable about the periphery of the hand wheel, a feed stop abutment on said control member arranged to be engaged by the feed stop pin to provide a positive stop against further feed of the hand wheel, a backing-off stop abutment on said control member arranged in the path of said backing-off pin to limit the backing-off movement of the hand wheel, and a cam surface on said control member arranged in the path of said backing-off pin during the movement of the hand wheel in the direction of feed to move said control member out of the path of the pin.
47. In a grinding machine, the combination with a work holder, of a grinding wheel spindle, a spindle carriage movable toward and away from the work holder, a cross feed mechanism for advancing and retracting the grinding wheel with relation to the work comprising a hand wheel, a control member movably supported on the machine adjacent the hand wheel, means actuated thereby for controlling machine operation, a feed stop pin on the hand wheel, a backing-off stop pin adjustable about the periphery of the hand

wheel, a feed stop abutment on said control member arranged to be engaged by the feed stop pin to provide a positive stop against further feed of the hand wheel, a backing-off stop abutment 5 on said control member arranged in the path of said backing-off pin to limit the backing-off movement of the hand wheel, and a cam surface on said control member arranged in the path of said backing-off pin for actuating the control 10 member upon movement of the pin into engagement with the backing-off stop abutment.

48. In a grinding machine, the combination with a work holder, of a grinding wheel spindle, a spindle carriage movable toward and away from 15 the work holder, a cross feed mechanism for advancing and retracting the grinding wheel with relation to the work comprising a hand wheel, a reciprocable feed pawl, ratchet teeth on the wheel to be engaged by the pawl, a stop surface on the 20 hand wheel arranged to render the pawl inoperative to further rotate the ratchet, means for reciprocating the pawl, a slide having formed on opposite sides thereof feed and backing-off stop abutments, and a cam surface overlying said feed 25 stop abutment, means actuated thereby for controlling machine operation, a stop pin on the hand wheel of a length to engage said feed stop abutment without engaging said overlying cam surface upon the engagement of the pawl with 30 the stop surface to provide a positive stop against further feed of the hand wheel, and a second pin supported adjustably about the periphery of the hand wheel arranged for engagement with said backing-off abutment to limit the backing-off 35 movement of the hand wheel and of a length to engage with said cam surface during the feeding movement of the hand wheel to move the slide out of the path of said pin.

49. In a grinding machine, the combination of 40 a work support, a grinding wheel spindle, a spindle carriage movable toward and away from the work, a cross feed mechanism for advancing and retracting the grinding wheel with relation to the work comprising a rotary feed 45 member, a depth feed stop pin on the feed member, a backing-off stop pin on the feed member, a control slide supported adjacent the feed member having on one side thereof a feed stop abutment to engage the feed stop pin, and on the other side thereof a cammed slide actuating surface and backing-off stop abutment for engagement by 50 said backing-off stop pin, and a control device for the machine actuated by the movement of the slide.

50. In a grinding machine, the combination of 55 a work support, a grinding wheel spindle, a spindle carriage movable toward and away from the work, a cross feed mechanism for advancing and retracting the grinding wheel with relation to the work comprising a rotary feed member, a depth feed stop pin on the feed member, a backing-off stop pin on the feed member, a control slide supported adjacent the feed member having on one side thereof a feed stop abutment to engage the feed stop pin, and on the other side thereof a cammed slide actuating surface and backing-off stop abutment for engagement by 60 said backing-off stop pin, spring means for returning the slide upon movement of the rotary feed member and backing-off pin away from said abutment and cammed surface, and a control device for the machine actuated by the movement and return of said slide.

51. In a grinding machine, the combination of 65 a work supporting assembly including a recipro-

cable work table and a rotary work holder carried thereon, means for controlling the operation of said table and work holder to impart a recurrent cycle of positioning movements to the work, a grinding wheel spindle, a wheel spindle carriage, a cross feed mechanism including a hand wheel for imparting feeding and backing-off movements to the carriage, a reciprocable feed pawl, ratchet teeth on the wheel to be engaged by said pawl, a stop surface on the hand 10 wheel arranged to render the pawl inoperative to further rotate the ratchet, means for reciprocating the pawl, a control element for the work supporting assembly to start and stop movement of the work located on the machine adjacent the 15 hand wheel, and a cooperating stop member adjustably supported on the hand wheel to engage with and actuate said start and stop control element at the limit of the reverse movement of the hand wheel in backing off the carriage to stop 20 work movement, and upon advancing the hand wheel from said retracted position to put the work assembly in operation to move the work.

52. In a grinding machine, the combination of 25 a work supporting assembly including a reciprocable work table and a rotary work holder carried thereon, means for controlling the operation of said table and work holder to impart a recurrent cycle of positioning movements to the work, a grinding wheel spindle, a wheel spindle carriage, a cross feed mechanism including a hand wheel for imparting feeding and backing-off movements to the carriage, a reciprocable feed pawl, ratchet teeth on the hand 30 wheel to be engaged by said pawl, a stop surface on the hand wheel arranged to render the pawl inoperative to further rotate the ratchet, means for reciprocating the pawl, a slide having formed thereon a depth stop abutment and an actuating cam surface, connections controlled by said 35 slide for controlling the assembly to start and stop work movement, a stop pin on the hand wheel arranged for engagement with said stop abutment upon the engagement of the pawl with said stop surface to provide a positive stop 40 against further feed of the hand wheel, a second pin supported on the hand wheel arranged upon rotation of the hand wheel in a reverse direction in backing off the grinding wheel for engagement with said cam surface of the slide to stop the 45 work movement.

53. In a grinding machine, the combination of 55 a work supporting assembly including a reciprocable work table and a rotary work holder carried thereon, means for controlling the operation of said table and work holder to impart a recurrent cycle of positioning movements to the work, a grinding wheel spindle, a wheel spindle carriage, a cross feed mechanism including a hand wheel for imparting feeding and backing-off 60 movements to the carriage, a reciprocable feed pawl, ratchet teeth on the hand wheel to be engaged by said pawl, a stop surface on the hand wheel arranged to render the pawl inoperative to further rotate the ratchet, means for reciprocating the pawl, a slide having formed thereon a stop abutment and an actuating cam surface, connections for controlling the work assembly to start and stop work movement and rendered operative by the movement of said slide in one 65 direction to start the work movement and rendered operative by the movement of the slide in an opposite direction to stop the work movement, spring means tending normally to maintain said slide and connections in running position 70

tion, a stop pin on the hand wheel arranged for engagement with said stop abutment upon the engagement of the pawl with said stop surface to provide a positive stop against further feed of the hand wheel, and a second stop pin adjustably supported on the hand wheel for a fully retracted position of the hand wheel and carriage controlled thereby to engage with and move said slide against the pressure of said spring means to stop the work movement.

54. In a grinding machine, the combination with a work holder, a grinding wheel spindle, a spindle carriage movable toward and away from the work, a cross feed mechanism for advancing and retracting the grinding wheel with relation to the work comprising a hand wheel and connections actuated thereby for moving the carriage, a wheel carriage rapid movement for imparting an additional movement to the carriage through a predetermined distance toward or away from the work, a manually operable control for the rapid movement, a stop device for limiting the advancing movement of the hand wheel at depth, a backing-off stop device for limiting the movement of the hand wheel in a reverse direction in backing off the carriage, an automatic control element for said wheel carriage rapid movement supported on the machine adjacent the hand wheel, means rendered operative by the movement of the hand wheel to its fully retracted position for actuating the control element to retract the carriage, and by a relatively slight forward movement of the hand wheel from said fully retracted position to actuate the control element for rapidly advancing the carriage, and a manually operable selector device shiftable to connect said automatic control element or alternatively said manually operable control element to actuate the rapid movement.

55. In a grinding machine, the combination with a work holder, a grinding wheel spindle, a spindle carriage movable toward and away from the work, a cross feed mechanism for advancing and retracting the grinding wheel with relation to the work comprising a hand wheel and connections actuated thereby for moving the carriage, a wheel carriage rapid movement for imparting an additional movement to the carriage through a predetermined distance toward or away from the work, a reciprocable feed pawl, ratchet teeth associated with the hand wheel to be engaged by said pawl, a stop surface on the hand wheel arranged to render the pawl inoperative to further rotate the ratchet, means for reciprocating the pawl, means under the control of the operator to move said pawl to inoperative position, means for limiting the movement of the hand wheel in reverse direction in backing off the carriage, a control element for said wheel carriage rapid movement supported on the machine adjacent said hand wheel, and means rendered operative by the movement of said hand wheel to its fully retracted position for actuating said control element to rapidly retract the carriage, and by a relatively slight forward movement of said hand wheel from said fully retracted position to actuate said control element to rapidly advance the carriage.

56. In a grinding machine, the combination of a longitudinally movable work table, a rotary work holder carried thereon, a grinding wheel spindle, a spindle carriage movable toward and away from the work holder, power means for reciprocating the table, power means for rotating the work holder, means for supplying coolant at

the point of grinding contact, manually operable means for advancing and retracting the wheel carriage with relation to the work comprising a hand wheel, a ratchet wheel connected to turn therewith, a reciprocable feed pawl, power means for reciprocating the pawl, power means for imparting a rapid movement to the spindle carriage through a predetermined distance alternatively toward or away from the work holder, and a control device rendered operative automatically by the movement of said hand wheel in advancing the carriage to render operative said power means for advancing the carriage, and simultaneously to start the table reciprocation, the work holder and the supply of coolant, and rendered operative by the movement of said hand wheel in retracting the carriage to render operative said power means to retract the carriage to stop the table reciprocation, the work holder and the supply of coolant and a manually operable selector device shiftable alternatively to render said automatic control means operative or inoperative to control said operation.

57. In a grinding machine, the combination of a work table, a rotary work holder carried thereon, a grinding wheel spindle, a spindle carriage movable toward and away from the work holder, a cross feed mechanism for advancing and retracting the grinding wheel with relation to the work comprising a hand wheel, a ratchet wheel connected to turn therewith, and a reciprocable feed pawl, a wheel carriage rapid movement for imparting an additional movement to the carriage through a predetermined distance toward or away from the work, power means for reciprocating the pawl, a stop surface associated with the ratchet wheel arranged to render the pawl inoperative to further rotate the ratchet, power means for rotating the work holder, means for supplying coolant at the point of grinding contact, and a control device actuated by a manual movement of the hand wheel advancing the carriage to render operative said power means for reciprocating the pawl, for rapidly advancing the carriage, and for starting the work holder and the supply of coolant, and actuated by a manual movement of the hand wheel retracting the carriage to stop pawl reciprocation, to rapidly move the spindle carriage away from the work holder, and to stop the work holder and the supply of coolant.

58. In a grinding machine, the combination of a longitudinally movable work table, power means for reciprocating the work table for traverse grinding of a work piece, a rotary work holder carried on the table, a grinding wheel spindle, a grinding wheel spindle carriage movable toward and away from the work holder, a cross feed mechanism for advancing and retracting the carriage with relation to the work comprising a hand wheel, a ratchet wheel connected to turn therewith, a reciprocable feed pawl and power means for reciprocating the pawl, and a control element rendered operative automatically by the movement of said hand wheel in advancing the carriage to connect said power means to reciprocate the table, and a manually operable selector device shiftable alternatively to render said automatic control means operative or inoperative to start table reciprocation.

59. In a grinding machine, the combination of a longitudinally movable work table, power means for reciprocating the work table for traverse grinding of a work piece, a rotary work holder carried on the table, a grinding wheel spindle, a

- wheel spindle carriage movable toward and away from the work holder, a cross feed mechanism for advancing and retracting the carriage with relation to the work comprising a hand wheel, a ratchet wheel connected to turn therewith, a reciprocable feed pawl and power means for reciprocating the pawl, and a control element rendered operative automatically by the movement of said hand wheel in retracting the carriage to render said table power reciprocating means inoperative, and a manually operable selector device shiftable alternatively to render said automatic control means operative or inoperative to stop table reciprocation.
60. In a grinding machine, the combination with a base, of a longitudinally movable work table, power means for reciprocating the work table for traverse grinding of a work piece, a rotary work holder carried on the table, a grinding wheel spindle, a grinding wheel spindle carriage movable toward and away from the work holder, a cross feed mechanism for advancing and retracting the carriage with relation to the work comprising a hand wheel, a ratchet wheel connected to turn therewith, a reciprocable feed pawl and power means for reciprocating the pawl, a control element movable to render said table power reciprocating means alternatively operative or inoperative, and means actuated by the movement of said hand wheel in advancing the carriage to operate said control element to start table reciprocation, and actuated by the movement of said hand wheel in retracting the carriage to operate said control element to stop table reciprocation, and a manually operable selector device shiftable alternatively to render said automatic control means operative or inoperative to control said operations.
61. In a grinding machine, the combination with a base, of a longitudinally movable work table, power means for reciprocating the work table for traverse grinding of a work piece, a rotary work holder carried on the table, power means for rotating the work holder, a grinding wheel spindle, a grinding wheel spindle carriage movable toward and away from the work holder, a cross feed mechanism for advancing and retracting the carriage with relation to the work comprising a hand wheel, a ratchet wheel connected to turn therewith, a reciprocable feed pawl and power means for reciprocating the pawl, a control element actuated by the movement of said hand wheel in advancing the carriage to render operative said power means to start the work holder and table, and actuated by movement of said hand wheel in retracting the carriage to stop the work holder and table and a manually operable selector device shiftable alternatively to render said automatic control means operative or inoperative to control said operations.
62. In a grinding machine, the combination of a longitudinally movable work table, a rotary work holder carried thereon, a grinding wheel spindle, a spindle carriage movable toward and away from the work holder, power means for reciprocating the table, power means for rotating the work holder, a cross feed for the wheel spindle carriage including a manually operable cross feed member, a cross feed rapid movement for moving the carriage through a predetermined distance toward and away from the work, a manually operable device for controlling each of the operations comprising said work holder rotation, table reciprocation, and the cross feed rapid movement, a separate automatic control device for controlling the rapid movement independently of said manually operable devices rendered operative by the movement of said cross feed member in advancing the carriage to rapidly advance the carriage, and rendered operative by the movement of said cross feed member in retracting the carriage to rapidly retract the carriage, and a manually operable selector device shiftable alternatively to render said automatic control device operative or inoperative to control said rapid movement.
63. In a grinding machine, the combination of a longitudinally movable work table, a rotary work holder carried thereon, a grinding wheel spindle, a spindle carriage movable toward and away from the work holder, power means for reciprocating the table, power means for rotating the work holder, a cross feed for the wheel spindle carriage including a manually operable cross feed member, a cross feed rapid movement, manually operable devices for controlling each of the operations comprising said work holder rotation, table reciprocation, and cross feed rapid movement, a separate automatic control device rendered operative by the movement of said cross feed member in advancing the carriage to start all of said operations and rendered operative by the movement of said cross feed member in retracting the carriage to discontinue all of said operations, and a manually operable selector device shiftable alternatively to render said automatic control device operative or inoperative to control all of said operations.
64. In a grinding machine, the combination of a rotary work holder, a grinding wheel spindle, a spindle carriage movable toward and away from the work holder, power means for rotating the work holder, power means for supplying coolant at the point of grinding contact, a cross feed for the wheel spindle carriage including a manually operable cross feed member, a cross feed rapid movement, manually operable devices for controlling each of the operations comprising said work holder rotation, coolant supply and cross feed rapid movement, a separate automatic control device rendered operative by the movement of said cross feed member in advancing the carriage to start said operations including a rapid advance of the carriage, and rendered operative by the movement of said cross feed member in retracting the carriage to discontinue said operations and to rapidly retract the carriage, and a manually operable selector device shiftable alternatively to render said automatic control device operative or inoperative to control said operations.
65. In a grinding machine, the combination of a rotary work holder, a grinding wheel spindle, a spindle carriage movable toward and away from the work holder, power means for rotating the work holder, a cross feed for the wheel spindle carriage including a manually operable cross feed member, a cross feed power rapid movement, manually operable devices for controlling each of the operations comprising said work holder rotation and cross feed rapid movement, a separate automatic control device rendered operative by the movement of said cross feed member in advancing the carriage to start said holder rotation and rapid advance of the carriage, and rendered operative by the movement of said cross feed member in retracting the carriage to stop holder rotation and to rapidly retract the carriage, and a manually operable selector device shiftable alternatively to render said automatic control device operative or inoperative to control said operations.

vice operative or inoperative to control said operations.

66. In a grinding machine, the combination of a reciprocable work table, a rotary work holder carried thereon, a grinding wheel spindle, a spindle carriage movable toward and away from the work holder, power means for reciprocating the table, power means for rotating the work holder, a cross feed for the wheel spindle carriage including a manually operable cross feed member, a cross feed power rapid movement for moving the carriage a predetermined distance toward and away from the work, manually operable devices for controlling independently each of the operations comprising said work holder rotation, table reciprocation and cross feed rapid movement, a separate automatic control device and connections rendered operative by the movement of said cross feed member in advancing the carriage to start said operations including the rapid advance of the spindle carriage, and rendered operative by the movement of said cross feed member in retracting the carriage to rapidly retract the carriage and discontinue said operations, a manually operable selector device shiftable alternatively to render said automatic control device operative or inoperative to control said operations, and a stop control acting when rendered operative to render said automatic control devices inoperative to start table reciprocation.

67. In a grinding machine, the combination with a rotating grinding wheel, of a reciprocable work table, means for reciprocating the table comprising a variable speed motor and driving connections including a fast-slow clutch, a variable speed control for the motor, a selector control for determining the position of the clutch, wheel truing means carried by the table, and a truing control for the machine comprising a manually operable selector device having alternative operative and inoperative positions, and connections therefrom for shifting the motor to a minimum speed and for positioning said clutch in slow position independently of the setting of the motor speed and clutch controls.

68. In a grinding machine, the combination with a rotating grinding wheel, of a reciprocable work table, means for reciprocating the table comprising a variable speed direct current motor and driving connections including a fast-slow clutch, a rheostat to control the speed of the motor, a selector control comprising a manually operable switch element and a solenoid controlled thereby for determining the position of the clutch, wheel truing means carried by the table, and a truing control for the machine comprising a manually operable selector device having alternative operative and inoperative positions, and electrical connections for shifting said motor to a minimum speed position independently of said rheostat and acting on said solenoid to position the clutch in slow position independently of the motor speed and clutch manual control.

69. In a grinding machine having a reciprocable table and a rotating grinding wheel, wheel truing means carried by the table, means for supplying coolant at the point of grinding contact, power means for reciprocating the table, a manually operable device for starting and stopping the table reciprocation, a normally independent control device for turning on and shutting off the supply of coolant, a truing control for the machine comprising a manually operable selector device having alternative truing and inoperative

positions, and connections actuated thereby for connecting said table reciprocating starting and stopping device simultaneously to turn on and shut off the supply of coolant.

70. In a grinding machine, the combination with a rotating grinding wheel, of a reciprocable work table, a rotary work holder carried thereon, means for supplying coolant at the point of grinding contact, a starting and stopping control for the table reciprocation, a starting and stopping control for the work holder including connections normally operative to start and stop the supply of coolant, wheel truing means carried on the table, and a truing control for the machine comprising a manually operable selector device having alternative truing and inoperative positions and connections actuated thereby for connecting the table starting and stopping control for simultaneously turning on and shutting off the supply of coolant.

71. In a grinding machine having a reciprocable work table and a rotating grinding wheel, means for reciprocating the table comprising a variable speed driving means, a manually operable control for adjusting said driving means to any one of a plurality of predetermined speeds, wheel truing means carried by the table, means for supplying coolant at the point of grinding contact, a manually operable device for starting and stopping the table reciprocation, a normally independent control device for turning on and shutting off the supply of coolant, and a truing control for the machine comprising a manually operable selector device having alternative truing and inoperative positions, and connections actuated thereby for adjusting the table drive to a predetermined truing speed independently of said manually operable control, and for connecting said table starting and stopping device simultaneously to turn on and shut off the supply of coolant.

72. In a grinding machine having a reciprocable work table and a rotating grinding wheel, a grinding wheel carriage movable toward and away from the work table, wheel truing means carried by the table, a cross feed for the grinding wheel, a cross feed rapid movement comprising means for moving the carriage a predetermined distance alternatively toward or away from the work, control means for said said rapid movement, a wheel truing control for the machine comprising a manually operable selector device having alternative truing and inoperative positions, and connections controlled thereby to render said control means for the cross feed rapid movement inoperative.

73. In a grinding machine having a reciprocable work table and a rotating grinding wheel, wheel truing means carried by the table, power means for driving the table, means for braking and reversing the direction of table drive, means for delaying the operation of said reversing means to provide a dwell in the operation of the table upon reversal, means under the control of the operator adjustable to produce predetermined variations in the amount of dwell, a truing control for the machine comprising a selector device having alternative truing and inoperative positions, and connections rendered operative by the movement of said selector device to truing position to eliminate said dwell independently of the setting of said dwell adjusting means.

74. In a grinding machine having a reciprocable work table and a rotating grinding wheel, wheel truing means carried by the table, means for reciprocating the table comprising a reversible variable speed direct current motor, a rheostat ad-

justable to produce a plurality of motor speeds, a table reversing circuit including braking and reversing switch connections for the motor, electrical means for delaying the operation of said reversing switch to provide a dwell in the table movement upon reversal, means for varying the amount of said dwell comprising a manually operable control element and switch connections controlled thereby for adjusting said electrical means to produce predetermined variations in the amount of the dwell produced thereby, a truing control for the machine comprising a selector device having alternative truing and inoperative positions, and switch connections rendered operative by the movement of said selector device to truing position for disconnecting said electrical means to eliminate the dwell, and to connect the motor for operation at a predetermined truing speed independently of the setting of the rheostat.

75. In a grinding machine, the combination of a reciprocable work table, a rotary work holder carried thereon, a rotary grinding wheel spindle, a wheel carriage movable toward and away from the work, wheel truing means carried by the table, power means for reciprocating the table, a manually operable control to start and stop table reciprocation, a cross feed for feeding the carriage and spindle carried thereby toward the work, a plunge cut control device including a manually operable element movable to prevent the operation of said manually operable control to start the table, a wheel truing control for the machine comprising a selector device having truing and inoperative positions, and connections controlled thereby to disconnect said plunge cut control device and to re-establish said table starting and stopping control.

76. In a grinding machine, the combination of a reciprocable work table, a rotary work holder carried thereon, a rotary grinding wheel spindle, a wheel carriage movable toward and away from the work, wheel truing means carried by the table, power means for reciprocating the table, a cross feed for feeding the carriage toward the work, an electrical control system including electrical connections under the control of the operator for starting and stopping the table, a plunge cut control device including a manually operable plunge cut control switch movable to disable said electrical connections for starting the table, a wheel truing control for the machine comprising a selector device having alternative truing and inoperative positions, and electrical connections controlled by movement of the selector device to truing position to re-establish said electrical connections under the control of the operator for starting the table.

77. In a grinding machine, the combination of a reciprocable work table, a rotary work holder carried thereon, a rotary grinding wheel spindle, a wheel carriage movable toward and away from the work, wheel truing means carried by the table, a reversible electric motor and connections including a clutch for reciprocating the table, a cross feed for feeding the carriage toward the work, a starting and stopping control for the table including electrical connections for starting and stopping the table motor and simultaneously for engaging and disengaging said clutch, a plunge cut control device including a manually operable plunge cut control switch movable to disable said electrical connections to engage the clutch, a wheel truing control for the machine comprising a selector device having alternative truing and

inoperative positions, and electrical connections rendered operative by the movement of said truing control to truing position to connect said table control for engaging and disengaging the clutch independently of the position of said plunge cut control switch.

78. In a grinding machine having a reciprocable work table and a rotating grinding wheel, wheel truing means carried by the table, a variable speed reversible electric motor for driving the table, means for reversing the motor to reverse the direction of table drive, means for slowing the motor to a predetermined slow rate prior to reversal, means under the control of the operator for starting and stopping table reciprocation, a wheel truing control for the machine comprising a selector device having alternative truing and inoperative positions, and connections rendered operative by the movement of said control to truing position to render said means for slowing the motor inoperative.

79. In a grinding machine having a reciprocable work table and a rotating grinding wheel, wheel truing means carried by the table, a variable speed electric motor for driving the table, means under the control of the operator for determining the motor speed, means for reversing the motor to reverse the direction of table drive, means for slowing the motor to a predetermined slow rate prior to reversal, means under the control of the operator for starting and stopping the table reciprocation, a wheel truing control for the machine comprising a selector device having alternative truing and inoperative positions, and connections rendered operative by the movement of said control to truing position to render said means for slowing the motor inoperative, and to connect said motor for operation at a predetermined truing speed.

80. In a grinding machine having a reciprocable work table and a rotating grinding wheel, wheel truing means carried by the table, a variable speed reversible electric motor for driving the table, means for reversing the motor to reverse the direction of table drive, means under the control of the operator for determining the motor speed, connections for driving the table from the motor including a fast-slow clutch, means under the control of the operator for determining the position of the clutch, means for slowing the motor to a predetermined slow rate prior to reversal, means under the control of the operator for starting and stopping the table reciprocation, a wheel truing control for the machine, a manually operable selector device having alternative truing and inoperative positions, and connections rendered operative by the movement of said control to truing position to render said means for slowing the motor inoperative, to shift said clutch to slow position, and to connect said motor for operation at a predetermined truing speed.

81. In a grinding machine, the combination of a reciprocable work table, a rotary grinding wheel spindle, a wheel carriage movable toward and away from the work, wheel truing means carried by the table, variable speed driving means for reciprocating the table, a manually operable control for determining the rate of table travel, a cross feed for moving the carriage and spindle carried thereby toward and away from the work, a manually operable device to start and stop the table reciprocation, a plunge cut control device adjustable by the operator to render said table starting and stopping means inoperative to start the table, a wheel truing control for the machine

comprising a manually operable selector device having alternative truing and inoperative positions, and connections controlled thereby rendered operative by the movement of said truing control to true position to render said plunge cut control device inoperative and to connect said variable speed drive to operate the table at a predetermined truing speed independently of the setting of said table speed control and plunge cut control device.

82. In a grinding machine, the combination of a reciprocable work table, a rotary grinding wheel spindle, a wheel carriage movable toward and away from the work, a cross feed for moving the carriage toward and away from the work, a variable speed reversible electric motor and connections including a clutch for reciprocating the table, a manually operable table starting and stopping control including connections for starting and stopping the motor and simultaneously for engaging and disengaging the clutch, a manually operable control for adjusting the motor speed, a plunge cut control device including a manually operable plunge cut control switch movable to disable said electrical connections for engaging the clutch, wheel truing means carried by the table, a wheel truing control for the machine comprising a manually operable selector device having alternative truing and inoperative positions, and electrical connections rendered operative by the movement of said truing control to truing position to connect the table starting and stopping control to engage the clutch independently of the setting of the plunge cut switch and to adjust the motor to a minimum speed independently of the setting of said motor speed control.

83. In a grinding machine, the combination of a reciprocable work table, a rotary grinding wheel spindle, a wheel carriage movable toward and away from the work, wheel truing means carried by the table, a variable speed electric motor for reciprocating the table, connections for driving the table from the motor including a fast-slow clutch, means under the control of the operator for adjusting the speed of the motor, means under the control of the operator for shifting the clutch, means under the control of the operator for starting and stopping the table reciprocation, a cross feed for moving the carriage towards and away from the work, a plunge cut control device including a manually operable element movable to render said table starting and stopping means inoperative to start the table, a wheel truing control for the machine comprising a manually operable selector device having alternative truing and inoperative positions, and connections rendered operative by the movement of said truing control to truing position to render said plunge cut control device inoperative, to shift said clutch to slow position, and to connect said motor for operation at a predetermined truing speed.

84. In a grinding machine, the combination of a reciprocable work table, a rotary grinding wheel spindle, a wheel spindle carriage movable toward and away from the work, wheel truing means carried by the table, means for axially reciprocating the spindle comprising a spindle reciprocating member, driving connections for driving said member from the spindle including a clutch, a solenoid for controlling the position of said clutch to start and stop spindle reciprocation, a manually operable control device including switch connections to said solenoid adjustable to start and stop spindle reciprocation, a wheel truing control for

the machine comprising a manually operable selector device having alternative truing and inoperative positions, and electrical connections rendered operative by movement of the truing control to truing position independently of said control device to stop spindle reciprocation.

85. In a grinding machine, the combination of a work supporting assembly comprising a reciprocable work table, a rotary work holder thereon, means for controlling the operation of the table and work holder to impart a recurrent cycle of positioning movements to the work, a grinding wheel spindle, a wheel spindle carriage movable toward and away from the work, means for supplying coolant to the point of grinding contact, a wheel carriage rapid movement, separate manual controls for controlling the operation of each of said table, work holder, and rapid movement, a manually operable cross feed mechanism for imparting feeding and backing-off movements to the carriage, a control device and connections therefrom rendered operative by the advancing movement of the cross feed for controlling each of said table and work holder to start movement of the work and to rapidly advance the carriage, and by the backing-off movement of the cross feed to stop the movement of the work, and to retract the carriage at a rapid rate, a selector device movable alternatively to render said control device operative or inoperative, and a truing control for the machine comprising a manually operable selector element having alternative truing and inoperative positions, and connections therefrom to disconnect said control device, to render the cross feed rapid movement inoperative, and to connect the manually operable table control to start and stop table reciprocation.

86. In a machine tool of the type having a work-carrying and a tool carrying head, one of which has a relatively rapid positioning movement and a relatively slow feeding movement with respect to the other, that construction of the mechanism for moving the movable slide comprising a shaft having a threaded connection therewith, an abutment for limiting the positioning movement of said shaft, devices having a spring connection with said shaft for moving it axially against said abutment, and a shaft rotating device having a sliding connection with said shaft for rotating it irrespective of its axial movement.

87. In a grinding machine of the type having slow feeding mechanism for relative approach of the wheel and work and having quick acting means for separating the wheel from its cutting contact with the work, a wheel carrying slide, a threaded screw for effecting a slow feeding movement of the slide, a stop to limit the axial movement of the screw in the direction causing approach of the wheel and work, mechanical operating means including a yielding element for causing axial movement of the screw without rotation thereof to effect quick approach and separation of the wheel from the work, said mechanical means overtravelling the screw in the direction in which motion is arrested by the stop, such overtravel being permitted by yielding of said yielding element, ratchet means for rotating the screw, and means associated with the rotating means to permit a free endwise movement of the screw with respect to the rotating means.

88. In a grinding machine of the type described, a wheel carrying slide, a threaded screw for effecting slow feeding movement of the slide,

means for causing axial movement of the screw without rotation thereof including a flanged sleeve carried by the screw, a lever engageable with the flange of the sleeve, a stop to limit the axial movement of the screw in one direction, means for moving said lever to hold the screw against said stop, means to rotate the feed screw when the screw is so held against the stop.

89. In a grinding machine of the type described, a wheel carrying slide, a reciprocable screw having threaded connection with the slide,

means for rotating the screw to cause relatively slow feeding movement of the slide, mechanical means having a relatively fixed stroke for reciprocating the screw axially, a stop limiting the reciprocation of the screw, and a yielding connection between the screw and said mechanical means to permit motion of the mechanical means after the screw has been arrested by contact with the stop.

MAXWELL I. MATHEWSON. 10
AUGUST L. KRAUSE.

CERTIFICATE OF CORRECTION.

Patent No. 2,165,898.

July 11, 1939.

MAXWELL I. MATHEWSON, ET AL.

It is hereby certified that error appears in the printed specification of the above numbered patent requiring correction as follows: Page 19, second column, line 13, claim 1, strike out the words and syllable "with a grinding wheel spindle, a rotary head—" and insert the same after "combination" in line 11, same claim; and that the said Letters Patent should be read with this correction therein that the same may conform to the record of the case in the Patent Office.

Signed and sealed this 11th day of May, A. D. 1940.

(Seal)

Henry Van Arsdale,
Acting Commissioner of Patents.

means for causing axial movement of the screw without rotation thereof including a flanged sleeve carried by the screw, a lever engageable with the flange of the sleeve, a stop to limit the axial movement of the screw in one direction, means for moving said lever to hold the screw against said stop, means to rotate the feed screw when the screw is so held against the stop.

89. In a grinding machine of the type described, a wheel carrying slide, a reciprocable screw having threaded connection with the slide,

means for rotating the screw to cause relatively slow feeding movement of the slide, mechanical means having a relatively fixed stroke for reciprocating the screw axially, a stop limiting the reciprocation of the screw, and a yielding connection between the screw and said mechanical means to permit motion of the mechanical means after the screw has been arrested by contact with the stop.
